UNITED STATES PATENT OFFICE.

EDMUND C. MORGAN, OF CHICAGO, ILLINOIS.

MINING-MACHINE.

1,271,199.

Specification of Letters Patent.

Patented July 2, 1918.

Application filed January 17, 1912. Serial No. 671,601.

To all whom it may concern:

Be it known that I, EDMUND C. MORGAN, a citizen of the United States, residing at Chicago, in the county of Cook and State 5 of Illinois, have invented certain new and useful Improvements in Mining-Machines, of which the following is a specification.

This invention relates to improvements in mining machinery particularly adapted 10 to dislodge material to be mined and convey away and load the material.

This invention further relates to an improved machine of this class having means for making cuts in the wall of the material 15 to be mined, and means for breaking down and dislodging the material; a further object being the provision of an improved machine of this class having means for automatically adjusting, feeding or positioning the breaking down means with relation to the material being operated upon.

A further object is to provide an improved machine of this class having means for controlling the breaking down means at will.

To the attainment of these ends and the accomplishment of other new and useful objects as will appear, the invention consists 25 in the features of novelty in substantially the construction, combination and arrangement of the several parts hereinafter more fully described and claimed, and shown in the accompanying drawings exemplifying the invention, and in which:

Figure 1 is a side elevation of the front 35 half of an improved machine of this character, constructed in accordance with the principles of this invention;

Fig. 2 is a side elevation of the remaining half of an improved machine of this class, 40 constructed in accordance with the principles of this invention;

Fig. 3 is a vertical longitudinal sectional view of Fig. 1;

Fig. 4 is a vertical longitudinal sectional 45 view of Fig. 2;

Fig. 5 is a rear elevation of part of the mechanism for adjusting the tension of the counterbalancing springs;

the right hand side of Fig. 2;
- Fig. 44 is a sectional view on line 44—44,
Fig. 4;
- Fig. 45 is a sectional view on line 45—45,
Fig. 44;
- Fig. 46 is a view partly in elevation and
partly in section of the lever for shifting
the clutch of one of the winding drums;
- Fig. 47 is a perspective view of a detail
of Figs. 45 and 46;
- Fig. 48 is a view partly in elevation and
partly in section of details of Figs. 45
and 46.
- Fig. 49 is an elevation of the end of the
swinging conveyer at the rear end of the
entire machine, as shown in Fig. 2.
- Fig. 50 is a sectional view on line 50—50,
Fig. 51;
- Fig. 51 is an enlarged elevation of the end
of the swinging conveyer showing the mech-
anism for tightening the conveyer element;
- Fig. 52 is a sectional view on line 52—52,
Fig. 4;
- Fig. 53 is a diagrammatic plan view of the
rope gear for shifting the machine laterally;
- Fig. 54 is a view partly in elevation and
partly in section of a portion of the feeding
or adjusting mechanism of the breaking
down means;
- Fig. 55 is a perspective view of a detail
of Fig. 54;
- Fig. 56 is a sectional view on line 56—56,
Fig. 54;
- Figs. 57 and 58 are elevations of details
of Figs. 54 and 56;
- Fig. 59 is a sectional view on line 59—59,
Fig. 56;
- Fig. 60 is a perspective view of a detail
of Figs. 54, 56 and 59;
- Fig. 61 is a plan of a detail of Fig. 7;
- Fig. 62 is a view of a detail of Fig. 59;

Fig. 54;
- Fig. 66 is a sectional view on line 66—66,
Fig. 54;
- Fig. 67 is an enlarged view of a part of
Fig. 54;
- Fig. 68 is a rear view of the block shown
- in Fig. 54 for guiding the latch bars of the
feeding mechanism of the breaking-down
means;
- Fig. 69 is a sectional view on line 69—69,
Fig. 49;
- Fig. 70 is a sectional view on line 70—70,
Fig. 49;
- Fig. 71 is a sectional view on line 71—71,
Fig. 72;
- Fig. 71^a is a side elevation of the con- 75
veyer frame detached from the machine;
- Fig. 72 is an enlarged detail view of the
end of one of the conveyers;
- Fig. 73 is a top plan view of Fig. 72;
- Fig. 74 is a sectional view on line 74—74, 80
Fig. 72;
- Fig. 75 is a sectional view on line 75—75,
- Fig. 76, showing the mechanism for adjust-
ing the position of the crank for recipro- 85
cating the breaking-down tools;
- Fig. 76 is a sectional view on line 76—76,
Fig. 75;
- Fig. 77 is an end elevation of a detail of
Figs. 75 and 76;
- Fig. 78 is an elevation of a detail of 90
Fig. 2;
- Fig. 79 is a sectional view on line 79—79,
Fig. 75;
- Fig. 80 is a view in elevation of the end
of the swinging arm for supporting the 95
vertical cutters;
- Fig. 81 is a plan view of the main con-
veyer frame mounted to slide longitudinally;
- Fig. 82 is a side view of Fig. 81;
- Fig. 83 is an end elevation looking from 100
the right hand end of Fig. 84;
- Fig. 84 is a top plan view of the adjust-
able chain cutter frame;
- Fig. 85 is a side elevation of Fig. 84;
- Fig. 86 is a sectional view on line 86—86, 105
Fig. 3;
- Fig. 87 is a sectional view on line 87—87,
Fig. 3;
- Fig. 88 is a sectional view on line 88—88,
Fig. 91; 110
- Fig. 89 is a sectional view on line 89—89,
Fig. 91;
- Fig. 90 is a sectional view on line 90—90,
Fig. 91;
- Fig. 91 is a side elevation of a detail of 115
Figs. 1 and 3;
- Fig. 92 is a side elevation of a detail of
Figs. 1 and 3;
- Fig. 93 is a sectional view on line 93—93,
Fig. 2, showing improved clutches for con- 120
trolling the slow advance and quick retrac-
tion of the horizontal chain cutter;
- Fig. 94 is a top plan view of one of the
clutch members shown in Fig. 93;
- Fig. 95 is a top plan view of another 125
clutch member shown in Fig. 93;
- Figs. 96 and 97 are sectional views of de-
tails of Fig. 93;
- Figs. 98 and 99 are plan views of details
of Fig. 93; 130

Fig. 100 is a detail sectional view of part of Fig. 93;

Fig. 101 is a perspective view of one of the springs in the clutch shown in Fig. 93;

5 Fig. 102 (Sheet 12) is a detail perspective view of the forward extremity of one of the sides of the conveyer frame shown in Figs. 6 and 8 on sheet with Figs. 17 to 23.

Referring more particularly to the drawings and in the present exemplification of this invention, the main support of the machine preferably comprises spaced side or frame members 5, 6, (Fig. 8) which are connected by transverse members 7 and supported by these transverse members to extend across the space between the side members 5 and 6, is a plate 8 which preferably terminates short of the forward extremities of the members 5, 6, as shown more clearly in Figs. 3 and 8, and which extremities are preferably beveled or inclined as at 9^a (see Figs. 1 and 3) so that the entire machine may be advanced readily into the room of the mine. Supported by the side members 5 and 6 are guide rails 9, which are held in position and preferably spaced from the side members 5 and 6 by means of uprights 10 which are rigidly attached to said members and to said rails. These guide rails 9 are preferably angular in cross-section to form flanges which project toward each other, and supported by these flanged portions in any suitable manner, are rack members 11 (see particularly Figs. 30 and 31), for a purpose to be hereinafter set forth, and these rack members 11 are removably secured and held in position in any suitable manner preferably by means of fastening devices 12 (Fig. 31).

40 The frame thus formed rests upon the floor of the mine, and the guide rails 9 receive and support the sliding structure which latter is of sectional structure and embodies what might be termed a cutter
 45 supporting frame designated generally by the reference numeral 13 in Fig. 84, and a conveyer frame designated generally by the reference numeral 14 in Fig. 81. The base of the frame 14 is of a width to rest upon
 50 the guide rails 9 as shown more clearly in Figs. 2, 30 and 31, and in order to prevent lateral displacement of the frame 14 with respect to the guide rails due to a twisting action which would be imparted thereto by
 55 the action of the cutters, or by any other means, this frame is provided with depending flanges 15, 16, (see particularly Figs. 2, 30, 31, 43 and 81) one of which flanges, the flange 15, is located adjacent the forward end of the frame 14, and the other flange 16 is located adjacent the rear of the frame 14, and these flanges overhang the guide-ways 9 and being spaced from each
 60 other longitudinally of the frame, the frame
 65 will be held in position on the guide-ways.

so that it may freely move thereon in a manner to be set forth. This frame 14 is located at the rear, and is adapted to slide freely upon the guide-rails 9 the entire length of the latter, and which rails are of a length slightly greater than the combined length of the entire superposed structure. The frame 13 is supported by the frame 14 for movement therewith, and for independent longitudinal movement with relation thereto, whereby a relative movement may be imparted to the frames 13 and 14 to adjust them with respect to each other. In order to accomplish these results, frame 14 (see particularly Figs. 3, 4, 8, 11 and 81), is provided with a portion 17 extending from the forward end thereof and is reduced laterally so that the reduced portion will extend between the guide rails 9, and the portion 17 is so formed with respect to the remaining portion of the frame 14, that it will be disposed below the plane of the bottom of the frame, or the portion of such frame which rests and moves upon the guide rails, as shown more clearly in Fig. 82. The frame 13 is of a size to extend between the guide rails 9, as shown more clearly in Figs. 3 and 11, and is provided with upwardly projecting portions 18 adjacent its rear end and which portions extend longitudinally of the frame and terminate short of the forward end thereof. These portions 18 are provided with outwardly projecting flanges 19 which are adapted to enter the guide-ways (Fig. 11) on the projecting portion 17 of the frame 14, and which guide-ways are formed by spaced inwardly projecting flanges 20, which flanges are spaced from the lower face of the portion 17 and are of a size to project into grooves formed between the flanges 17 and the top of the frame 13, as shown more clearly in Figs. 8 and 11. These flanges 20 serve to suspend or support the entire frame 13 and also permit of a relative movement of this frame with respect to the frame 14, and in order that this relative movement may be imparted thereto when the parts are assembled, and in the present exemplification of this invention, the frame 13 is provided between the upright portions 18 (see particularly Figs. 3, 8, 84 and 85) with partitions 21, 22 extending upwardly from the upper face of the frame, and spaced from each other longitudinally of the frame. These partitions are provided respectively with upright ribs or fins 23 and 24 oppositely disposed with respect to each other. An adjusting screw 25, (see also Fig. 28) is provided and is located between the ribs or fins 23 and 24. One extremity of the screw 25 engages and rests against one of the fins or ribs, (as that designated 24 in Fig. 8) and the other extremity is recessed or notched as at 26 (Fig. 28) and is

of a size to receive the other rib or fin 23 so that when the screw is placed in position, the notch 26 and the coöperating rib or fin 23 will hold the screw against rotation.

5 This screw 25 is supported from the portion 17 of the conveyer frame 14 by means of a cap member 27, shown more clearly in Figs. 3 and 29, and which cap member is provided with spaced depending bearings 28.

10 The cap member rests upon the upper face of the portion 17 of the conveyer frame 14 and is of a size to cover an opening 29 (Fig. 81) in the said portion, and through which opening the depending bearings 28 of the

15 cap member project, and the cap member is secured against displacement in any suitable manner, preferably by means of fastening devices 30. Threaded upon the screw 25 is a worm gear 31, (Figs. 3 and 8) and

20 this gear is located between the depending bearings 28, and being supported by the frame 17, a rotation thereof will cause the worm gear and the screw 25 to be adjusted relatively with respect to each other and

25 longitudinally with respect to the screw. Inasmuch as the worm gear cannot move with respect to the supporting structure, to wit; the conveyer frame 14, it will be manifest that a rotation of the worm gear will

30 cause the screw 25 to be fed through the worm gear, and inasmuch as the screw is connected with the frame 13, and also inasmuch as the screw passes loosely through the bearing members 28, it will be manifest

35 that the feeding of this screw 25 through the worm gear 31, will cause the cutter-supporting frame 13 to be adjusted relatively to the frame 14, in either direction of rotation of the worm gear. This

40 relative adjustment of the cutter-supporting frame 13 with respect to the conveyer frame 14 is for the purpose of tightening the horizontal cutter which makes the horizontal cuts or kerfs in the wall of the material to be mined. This cutter, in the

45 present exemplification of this invention, comprises an endless flexible member 31^a, (Fig. 8) preferably in the form of a chain embodying links, and passes around the

50 outer edge of the supporting frame 13 as shown more clearly in Figs. 2, 3, 8 and 52, and has detachably connected therewith, a series of tools, or cutters 32, which are arranged in different horizontal planes with

55 respect to each other, as shown more clearly in Fig. 1, so as to operate in different planes on the material to be mined and thereby make a cut or kerf of some width. The endless chain cutter thus described, is

60 supported by the frame 13 and travels in a groove or guideway 33 formed around the outer edge of the frame, (Fig. 85) and in order to hold the cutter in position and to form wear plates in the groove, strips or

65 members 34 are provided (see particularly

Figs. 3, 11 and 29) with which the endless members 31 contact. These members 34 may be removably secured in position in any suitable manner, preferably by means of fastening devices, such as bolts or rivets 70 which pass through suitable apertures or openings 35 (see Figs. 84 and 85) and engage the wear plates 34. The rear end of the endless chain cutter thus described passes around a sprocket wheel 35^a, (see particularly Figs. 30, 4 and 52) which latter is connected with an upright shaft 36 journaled in a suitable bearing 37 supported by the conveyer frame 14, the teeth of which sprocket wheel project into the links of the 80 endless chain 31^a. It will therefore be seen that with the above construction, when the cutter-supporting frame 13 is adjusted relatively to the conveyer frame 14, the endless flexible chain 31^a will be tightened or 85 loosened according to the adjustment of the cutter-supporting frame 13 with respect to the conveyer frame 14, inasmuch as the sprocket wheel 35^a is fixed with relation to the conveyer frame 14. The rotation of 90 this sprocket wheel 35^a will impart motion to the cutter, and the sprocket wheel receives its motion from mechanism which will be hereinafter more fully described.

Any suitable means may be provided for 95 rotating the shifting worm gear 31, and a simple and efficient means comprises a worm 38 (see particularly Figs. 3, 11 and 29), which is connected to a shaft 39, the latter being journaled adjacent one extremity in the cap member 27 while the other extremity of the shaft is journaled in a suitable bearing 40 connected with the cap member. The worm 38 meshes with the worm gear 31, and this worm 38 together with the shaft 39, are disposed in such positions that their axes will be inclined to the horizontal so that the free extremity 41 of the shaft will be elevated above the guide rails 9 in a convenient position for the operator, and the shaft is of such a length that the extremity 41 will be disposed adjacent the side of the main supporting frame and in a position when ready access may be had thereto. This extremity 41 is preferably angular in configuration for the reception of a wrench or tool by means of which the shaft may be rotated.

The front end of the cutter-supporting frame 13 is provided with an opening 41^a 120 therein (see particularly Figs. 8, 23 and 84) for a purpose to be hereinafter set forth, and the upper one of the flanges which form the groove or recess 33 at the forward end of the cutter-supporting frame 13, is formed by a removable plate 42 (see also Figs. 3, 22 and 23) which is held in position by fastening devices 43 for a purpose to be also set forth.

Motion is imparted to the shaft 36 (Fig. 130

30) to operate the cutters 32 by means of a motor-shaft 44, the motor being supported in a casing 45 carried by the conveyer frame 14 (see particularly Figs. 81 and 82), and the motor casing is so arranged that a portion thereof will depend below the frame to project into the space between the guide rails 9 (Figs. 2 and 4). The motor shaft 44 projects beyond the forward end of the motor casing and the forward extremity of this shaft is journaled in a suitable bearing, preferably in the bearing 37 as shown more clearly in Fig. 4. A pinion gear 46 is connected to the shaft 44, and this gear meshes with a bevel gear 47 secured to the shaft 36 for rotation therewith (see particularly Figs. 4 and 30). This gear 47 is preferably arranged above the bottom of the conveyer frame 14, and 20 when rotated by the motor, will operate the shaft 36 and the sprocket 35^a to impart motion to the endless flexible member or chain 31.

The structure thus far described is adapted to be moved upon the guide rails 9 by power transmitted through the intermeshing gears 46, 47 to advance or retract the cutter with respect to the material being operated upon. It is advisable in machines 30 of this class, to advance the cutter slowly into the material being mined, and to retract the cutter quickly, and in order to accomplish this, mechanism is provided which will now be described.

35 The sliding structure, including the conveyer frame 14 and cutter-supporting frame 13, receives its forward and backward movement through the medium of a shaft 48 (see particularly Figs. 4, 31 and 52) which is journaled in suitable bearings in the conveyer frame 14, or rather a portion of the frame which depends into the space between the guide rails 9. The extremities of this shaft project beyond the 45 sides of the conveyer frame 14 and carry gear wheels 49 which mesh with the racks 11 carried by the guide rails (Figs. 4 and 52) so that when the shaft 48 is rotated, the frames 13 and 14 will be advanced or retracted with respect to the main supporting 50 frame. This shaft 48 receives its motion from the shaft 36 through the medium of a large gear 50 (see particularly Fig. 9), which is connected for operation with the 55 small gear 57 (Fig. 30).

An upright shaft 51 is arranged on one side of the conveyer frame 14 and is journaled by one end in a step bearing 52 of the frame 14 (Fig. 30). The other end of 60 this shaft is journaled in a bearing in a plate or support 53 (see particularly Figs. 2 and 30), and which latter is held in position by means of suitable upright portions 54, 55 on the frame 14 to which it is secured 65 by suitable fastening devices 55^a (Figs. 2, 4,

81 and 82). The upright portions or supports 55 are formed by a portion of the motor casing 45 as shown more clearly in Fig. 82. This shaft 51 is connected with the shaft 48 for rotating the latter by means of a worm 56 carried by the shaft, (Fig. 30), and meshes with a worm gear 56^a carried by the shaft 48 (Fig. 31). The shaft 51 is adapted to be rotated in either direction from the shaft 36 at the will of the operator 75 and at different speeds. In order to accomplish this, there is provided a gear 57 (see particularly Figs. 30 and 93), which is loosely mounted upon the shaft and meshes with the gear 50. The gear 57 is provided with 80 a recess 58 in which is arranged fibrous material 59, and against this fibrous material and within the recessed portion is arranged an annular ring 60 having a groove 61 in its upper face. The recess 58 is provided 85 with an enlarged portion 62, the wall of which is provided with screw threads adapted to receive the threads on an annular nut or collar 63. The face of the latter which is adjacent the ring 60 is of a size to extend 90 across and form a closure for the groove 61, as shown more clearly in Fig. 93, and within this groove are any desired number of springs 64 which are curved longitudinally as shown, so that when the collar 63 95 is adjusted into the recess, the elastic members or springs 64 will be placed under tension and this will force the annular member 60 together with the fibrous material 59 toward the bottom of the recess 58 to form a 100 frictional connection between the parts for a purpose to be set forth. A similar gear 65 is loosely mounted upon the shaft 51 adjacent the gear 57, and this gear 65 is preferably of a diameter larger than the diameter 105 of the gear 57. The gear 65 is also provided with a recess 66 similar to the recess 58 in the gear 57 in which recess is arranged fibrous material 67 and an annular ring 68 similar to the elements 59, 60, and the member 68 is provided with a recess 69 similar 110 to the recess 61 in the member 60, in which recess 69 is arranged springs 64, and an annular member or collar 70 similar to the collar 63 is screwed into an enlarged portion 115 of the recess 66 to compress the springs 64 and force the member 68 and fibrous material 67 into frictional connection with the gear 65. Splined on the shaft 51 between the gears 57, 65 is a clutch member 71 having 120 diametrically disposed projecting portions 72 which are adapted to be projected through the collar 70 and into the annular member 68 to coöperate with shoulders or projecting portions 73, so that when the clutch member is thus actuated, the gear 65 will be yieldingly connected for rotation 125 with the shaft. The clutch member 71 is also provided with a downward projection 74 adapted to be projected through the col- 130

lar 63 and into the annular member 60 to co-operate with projecting portions or shoulders 75 to yieldingly connect the gear 57 for rotation with the shaft. The clutch member 71 is of such a size and the gears are so disposed with respect to each other, that when the clutch member is adjusted to connect one of the gears for rotation with the shaft, the other gear will be disconnected. In order to facilitate the operation of the clutch member 71 with respect to the gear 57, the lower face of the projection 74 of the clutch member is beveled or inclined as shown, and the upper faces of the projections 75 on the annular member 60, are also beveled or inclined. The tension created upon the springs 64 is sufficient, under normal conditions, to connect the respective gears 57, 65 for rotation with the shaft 51 when the clutch member 71 is properly positioned, but in the event that the traveling structure, including the cutter-supporting frame 13 and the cutter thereon, meets with any obstructions during the feed thereof, the frictional connection between the gears and the shaft will yield to permit the gears to rotate independently with respect to the shaft, although the clutch member 71 may be in a position to ordinarily lock the gear 57 with the shaft. The clutch member 71 may be shifted manually from either side of the machine, and in order to accomplish this, there is provided an ordinary yoke 86 (Fig. 9) on a rock shaft 76 journaled in suitable bearings 77 (see particularly Figs. 2, 9 and 31) on the frame 14, which rock shaft is of a length to extend entirely across the machine. Hand levers 78 are connected with this shaft 76 on opposite sides of the machine and in convenient positions for the operator. The clutch 71 may be also shifted automatically when the traveling structure reaches the limit of its forward and backward movements with respect to the main supporting frame. In order to accomplish this, there is provided an arm 79 which is connected with the shaft 76 which depends from the shaft preferably on the outside of the main supporting structure. Spaced stops 81 and 80 (see Figs. 1 and 2) are provided, one at the forward end of the machine, and the other adjacent the rear end, and in such positions that the arm 79 will engage the respective stops to be shifted thereby to rock the shaft 76 just as the supporting structure reaches the limit of its respective movements.

Inasmuch as the gear 57 is connected directly with the shaft 36 through the medium of the gear 50, the shaft 51, when the gear 57 is locked thereto, will be rotated in a certain direction. Motion is imparted to the gear 65 from the shaft 36 through the medium of a gear 82 (see particularly Figs. 9 and 30) connected with the shaft 36. This

gear 82 meshes with another gear 83 which has connected with it and for rotation therewith, a gear 84 which latter gear meshes with the gear 65, and these gears 83, 84 are preferably supported by an axle 85 journaled in a suitable bearing preferably in the support 53 (Fig. 30). Thus it will be seen that even though the shaft 36 and the gears 47, 50, 82, are continuously rotated, which will in turn continuously rotate the gears 57, 65, the sliding structure comprising the chain cutter will not advance or be retracted upon the main frame until the clutch member 71 has been shifted, and such shifting movement is under the direct control of the operator. The gear 65 operates to advance the cutter into the work while the gear 57 retracts the cutter, and inasmuch as this latter gear is of a diameter smaller than the diameter of the gear 50, the cutter will be retracted at a greater rate of speed than the speed of its advancing movement. Obviously, the clutch member 71 may be shifted by the ordinary yoke 86 which is connected with the shaft 76.

The conveyer, preferably of the endless type, is supported upon the traveling frame 14 and extends over substantially the entire length of the machine. The conveyer frame is preferably constructed of angle irons 87 (see particularly Figs. 86 and 87) spaced from each other, so that the laterally projecting portions 88 will be disposed toward and terminate short of each other. These angle irons 87 are held spaced from each other in any suitable manner, but preferably by means of supplemental angle irons 89 which are secured to the body portions of the angle irons 87 and are spaced from the laterally projecting portions 88 to form a runway for one of the runs of the endless conveyer designated generally by the reference numeral 90, and which conveyer comprises spaced endless flexible members which are connected together by the conveyer flights 91. A plate 92 is supported by and secured to the angle irons 89, and this plate also forms a support for the upper run of the conveyer. The lower run of the conveyer is supported by angle irons 93 which are also secured to the angle irons 87 and below the angle irons 89 to form spaces in which the lower run of the conveyer operates, and which spaces are located below the plate 92. The angle irons 93 along the intermediate portions of the conveyer are preferably arranged in close proximity to the angle irons 89, so that the lower run of the conveyer will be held close to the lower face of the plate 92 to prevent the lower run of the conveyer from contacting with or forming an obstruction to any of the other portions of the mechanism, and at the same time, keep the conveyer confined in a minimum space, as

shown more particularly in Figs. 3, 4 and 87. The angle irons 94 which are located adjacent the forward extremity of the conveyer frame, as shown more clearly in Figs. 5 3 and 86, are spaced some distance from the angle irons 89 so that the runs of the conveyer will be separated. Another pair of angle irons 95 (Fig. 3) are also supported by the angle irons 87 in advance of the angle irons 94, and these angle irons 95 are arranged in a horizontal plane and are secured to portions of the angle irons 87 which are also arranged in horizontal planes, while the remaining portions of the angle irons 15 87 and the angle irons 93—94, incline upwardly toward the rear of the conveyer, and the rear of the machine. The portion of the plate 92 adjacent the angle irons 95 is also disposed in a horizontal plane to 20 form a platform for the reception of the material which is dislodged. Mounted at the forward ends of the angle irons 95 are sprocket wheels 96 (Figs. 22 and 23) journaled in suitable bearings and over which 25 the endless flexible members 90 pass. Similar sprocket wheels 97 (Fig. 72) are also arranged at the other end of the conveyer frame and over which the endless flexible members 90 pass. The conveyer thus 30 constructed is removably supported upon the movable frame 13 in any suitable manner, preferably by means of uprights 98 (see Figs. 3, 20, 83, 84 and 85) in the form of ears or projections carried by the frame 13, and 35 fastening devices 99 (Fig. 20) in the form of bolts which pass through the angle irons 87 and have detachable engagement with the uprights or projections 98. The forward extremities of the angle irons 87 are 40 cut away, (Sheet 12), as shown in Fig. 102, to form shoulders 100 which pass under projecting lips or ledges 101 (see Figs. 21 and 84) at the forward extremities of the frame 13, adjacent the opening 41 so as to hold the 45 forward end of the conveyer frame from rising. These forward extremities of the angle irons 87 are also supported by means of projecting portions or shoulders 102 on the frame 13 and which shoulders extend 50 into the opening 41, as shown more clearly in Fig. 84. The rear extremity of the conveyer is supported by means of brackets 103 (see particularly Figs. 4, 65 and 71^a) secured to the outer faces of the angle irons 55 87, and which brackets engage and rest upon shoulders 104 carried by a frame 105, (which frame will presently be described) and fastening devices 106, preferably in the form of bolts, pass through ears or projections 107 and above the brackets 103, in such a manner as to coöperate with the shoulders 104 to hold the brackets in position. It will thus be seen that the forward 60 end of the conveyer is supported by the frame 13 and that the rear end of the con-

veyer is supported by the frame 14, and inasmuch as the brackets 103 rest upon the shoulders 104, it will be manifest that when the frame 13 is adjusted relatively to the frame 14, such adjustment will not be interfered with by the conveyer frame because the conveyer frame will slide upon the shoulder 104 to permit such adjustment. Furthermore, it will be noted that by detaching the fastening devices 99 (Fig. 20) at the forward end 70 of the conveyer, and the fastening devices 106 (Fig. 65), the entire conveyer frame and conveyer may be bodily removed from the machine. The forward end of the conveyer, or rather the portion adjacent the forward 75 extremities of the angle irons 95, terminates adjacent the forward wall of the opening 41 (see particularly Figs. 3 and 84), and in order to close the opening between the forward end of the frame 13 or rather the 80 forward wall of the opening 41 and the forward extremity of the conveyer to prevent the dislodged material from falling between the conveyer and the cutter frame, the plate 42 is provided and which plate 85 90 as has been already described, is detachably secured in position by means of the fastening devices 43.

In order to take up the slack of the endless conveyer, the sprocket wheels 97 which are located at the rear or discharge end of the conveyer, are mounted in adjustable bearings 108 (see particularly Figs. 2, 71^a, 72 and 74) which have sliding engagement with the conveyer frame and are adjustable 95 by means of adjusting devices 109, preferably in the form of screws, one extremity of which has engagement with a portion of the adjustable bearing 108 and is threaded and passes through an ear or projection 110 100 which is fixed with respect to the conveyer frame.

Motion is imparted to the endless conveyer from the same motor which operates the cutter already described, through suitable gearing, the gears 111 of which (see particularly Figs. 2 and 54) are supported by the frame 105. This frame 105, as shown more clearly in Fig. 2, is supported above the frame 53 and rests upon the frame 53, 115 at the points 112, 113, which points are so arranged that they will have engagement with the frame or support 53 directly over the points of bearing of the frame 53 upon the motor casing 44 and the uprights 54 120 on the frame 14, so that the fastening devices 56 which secure the frame or support 53 in position, will also secure the frame 105. This frame 105 also preferably has engagement with supports 114 in the form of 125 uprights on the frame 14, (see also Figs. 81 and 82) and is secured to these supports 114 by means of suitable fastening devices 115. Connected with one of the shafts 116 of the gears 111 (see also Fig. 31), and which 130

shafts are journaled in suitable bearings in the frame 105, is a sprocket wheel 117 over which a sprocket chain 118 passes, and this sprocket chain in turn passes over another sprocket wheel 119 (see Fig. 74) carried by the shaft 120 connected to which are the sprocket wheels 97, so that when the gears 111 are rotated, motion will be imparted to the endless conveyer. These gears 111 receive their motion from gears 121, 122 (see particularly Figs. 2 and 30) and which gears 122, 121 are journaled in suitable bearings in the frame or support 105, and are located on opposite sides of the machine 15 adjacent the respective gears 111. The gear 121 on one side of the machine receives its motion from the gear 65 (Fig. 30) through the medium of a gear 123 which is connected with the gear 65 for rotation therewith, and which gear 123 meshes with the gear 124 connected with the gear 121. The gear 65 as has been already described is continuously rotating and receives its motion through the gears 84, 83, 82, and shaft 20 25 30 35 40 45 50 55 60 65 70 75 80 85 90 95 100 105 110 115 120 the brake strap 327 to the long arcuate surface of the sector member 284. By applying sufficient force to the brake mechanism, the multiple pick machine will be prevented 5 from being fed upwardly notwithstanding the release of the latch mechanism, and therefore the operation of the pick machine may be repeated at the will of the operator while being held in a certain position. Furthermore, the operator can pull up the lever 309 at any time he desires to do so in order to release both of the reversely arranged latches and allow the pick machine to move down by gravity. Therefore, the operator 10 can so control the machine to produce an initial kerf at the base of the mine wall to facilitate subsequent successive dislodging operations as the pick machine is fed automatically upwardly step by step. If the operator chooses to avoid the application of the brake to prevent feeding operation upwardly, he can permit feeding motion to the extent of one step and then release the latch mechanism to let the pick machine go 15 back to initial position. This can be repeated as often as desired or until the coal immediately above the underkerf has been snubbed down to a sufficient extent. It is also evident that when the picks have been 20 brought back to substantially the rear limits of their strokes, they are fed upwardly provided the brake 327 is not applied. When the brake is applied, however, with sufficient force, it forms a locking means against any 25 feeding movement.

Arranged at the forward end of the machine are cutters designated generally by the reference numeral 150, which are provided for the purpose of making upright or 30 vertical cuts in the wall of the material to be mined, and these cutters are disposed slightly in the rear of the plane of the front cutting edge of the cutters 31, 32, the latter cutters being disposed between the cutting 35 planes of these vertical cutters. In the present exemplification of the invention, these cutters 150 are preferably in the form of disks having cutting tools 151 removably secured thereto, and the disks are arranged to 40 revolve about horizontal axes. The cutters 150 are supported by arms 152 and as the mounting and operation of each of these cutters and cutter-arms is the same, the specific description of one will apply equally as 45 well to both. In the present exemplification of this invention, two of these cutters are employed and each is provided with its own supporting arm. The arms 152 may be of any desired configuration but are preferably 50 of angle iron construction as shown more clearly in Fig. 30, having a journal 153 which journal has a bearing in the frame 105, and the portions 154 of the frame 105 in which the journal 153 has a bearing, serve as

bearings for the gears 121 and 122, as shown 55 more clearly in Fig. 30. In the present exemplification of this invention, the journal 153 is formed on a separate member 155 (see particularly Figs. 2 and 80) which is secured to the arms 152, but it is obvious 60 that if desired it may be formed integral. The cutters 150 are rotatably supported adjacent the forward ends of the arms 152, and the arms are of a length that the cutters 152 will be held and maintained in 65 proper cutting positions with respect to the cutters 31, 32, so that the latter, which cut horizontal cuts or kerfs, will operate upon the material slightly in advance of the cutters 150. The cutters 150 are supported for 70 adjustment longitudinally with respect to the arms for a purpose to be set forth, and in order to accomplish this, an adjustable bearing is provided. In the present exemplification of this invention, the cutter 150 is provided with a hub 156 (see particularly 75 Fig. 12) which is connected with the cutter in any suitable manner, preferably by means of a reduced portion 157 of the hub which passes through an opening in the body of 80 the cutter so that a flange 158 will engage and rest against one face of the cutter, and suitable fastening devices 159 are provided for securing the hub and cutter together. The hub 156 is provided with internal screw 85 threads and a sleeve 160 is provided with external screw threads on one side, which end is adapted to enter the hub 156 so that the threads thereon will engage the threads in the hub and thereby secure the two together. Supported by this sleeve 160 is a 90 sprocket wheel 161 which preferably abuts the end of the hub 156 and thereby serves as a means for limiting the adjustment of the sleeve 160 with respect to the hub 156 in one 95 direction. The other end of the sleeve 160 beyond the sprocket 161, is provided with a circumferential groove 162. This sleeve 160 receives a journal or projection 163 which projects laterally from a bearing member 100 164, and this bearing member is adjustably secured to the extremity of the arm 152 in any suitable manner, preferably by means of fastening devices 165 passing through a slot 166, in the bearing member, being 105 threaded into another member 167 which is carried by the arm 152. The bearing member 164 is adjusted longitudinally with respect to the arm 152 preferably by means of an adjusting screw 168, which is threaded 110 through the member 167 and has engagement with the bearing member 164, so that when the fastening devices 165 are loosened and the screw 168 adjusted in one direction, the member 164 will be adjusted with respect to the arm 152, after which the fastening devices 165 may be tightened and the parts will be thus held in their adjusted 115 position.

sitions. The cutter 150 is rotatably supported upon the journal 163, about which the sleeve 160 rotates. In order to hold this sleeve 160 and consequently the hub 156 and cutter 150 against displacement laterally, there is provided a fastening device 169 which is connected preferably with the bearing member 164 by means of a suitable fastening device 170, and the fastening device 169 is so located that it will project into the circumferential groove in the sleeve 160 and thereby lock the latter against displacement. The journal 163 is provided with a recess 171 opening through one end of the journal, which opening is closed by a removable closure 172, and a lubricant cup 173 (Figs. 3, 10 and 13) is provided which has connection with the recess 171 by means of which the bearing may be lubricated. The arms 152 are preferably of channel formation, as shown more clearly in Fig. 13, and a sprocket 161 is located within the channel, while the adjustable bearing member 164 extends across the channel and forms a closure so to speak at that point, to protect the sprocket against being struck by any falling material. A sprocket chain 174 passes over the sprocket 161 and is also located within the channel so that it will be protected thereby, and the other end of the sprocket chain passes over a sprocket wheel 175 (see particularly Figs. 4 and 30) carried by an axle 176 which is connected with the gears 121, 124 on one side, and gears 122, 130 on the other side of the machine, so that when these last mentioned gears are rotated in the manner, as has already been set forth, through the medium of the shaft 36, and the intermediate gears, the sprocket chains 174 will be operated to impart a rotary motion to the cutters 150. The object of the adjustable bearing member 164 carrying the bearing members which rotatably support the cutters 150, is to permit the cutters and bearings to be adjusted longitudinally with respect to the arms 152 and the sprockets 175, to take up the slack in the sprocket chains 174.

In addition to the rotary motion of the cutters 150 with respect to the arms 152 which is imparted thereto by the sprocket chains 174, these cutters are adapted for bodily oscillating movements vertically about the pivots formed by the journals 153 so that the cutters may be moved to command the entire vertical area of the material being operated upon, and this bodily oscillating movement is imparted to these cutters simultaneously with the other or rotary movement thereof. Any suitable mechanism may be provided for imparting this bodily oscillating movement, but a simple and efficient means will now be described. Inasmuch as the construction of the oscillating mechanism for each of the

arms is the same, the specific description of one of such mechanism, will apply equally as well to both, reference being had particularly to Figs. 1 to 4, 11, 24 to 27, 81 and 82.

Projecting upwardly from the reduced portion 17 of the frame 14, (Fig. 81) in advance of the pivots of the arms 152, and also in advance of the upright shaft 36 and extending transversely of the portion 17 of the frame, are spaced pairs of bearings 177 (Fig. 3) in which are journaled the axles 178 of gear wheels 179 (see particularly Fig. 11). The adjacent bearings of each pair are preferably smaller than the other bearings of the respective pairs to receive a reduced portion 180 of the axle which will operate to overcome the end thrust of the axle, and these axles are preferably hollow for the purpose of lightness. The axles 178 are held in their bearings by means of cap members 181 (see particularly Figs. 3, 6 and 11), which are supported by an extension 182 of the support 53 (Figs. 3, 4 and 6).

The gears 179 are provided for the purpose of oscillating the arms 152 about their pivots in a manner which will be presently described, and the gears receive their motion from the shaft 36 through the medium of a worm 183 (see Figs. 4 and 30) on the shaft 36, which worm meshes with a worm gear 184 (see Figs. 4 and 7) on a shaft 185 journaled in suitable bearings, preferably bearings 186 (see Figs. 81 and 82) in the uprights 54 on the frame 14, and this shaft 185 extends transversely with respect to the shaft 36. Gears 187 are mounted loosely on the shaft 185, and these gears mesh respectively with the gears 179. The shaft 185 is continuously rotated by the shaft 36 and in order to connect the gears 187 with the shaft 185 for rotation therewith, and to discontinue them from the shaft, clutch members 188 are provided, (see also Fig. 61) and these clutch members coöperate with clutch faces 189 carried by the gears 187. Operating levers 190 arranged in convenient positions for the operator, are provided for controlling the clutch members 188. By shifting the clutch members 188 so that both of the gears 187 will be locked for rotation with the shaft 185, both of the gears 179 will be rotated, and through the connections of these gears with the arms 152, which connections will be presently described, both of the arms 152 will be oscillated to oscillate both of the cutters 150. Should it for any reason be desired to render one of the cutters 150 inoperative, that is, with respect to its bodily oscillating movement, and maintain the other cutter 150 operative for its bodily movement, one of the clutches 188 may be shifted into position so that its respective gears 187 will be locked with respect to the shaft 185, and the other clutch may be shifted so as to unlock 180

its respective gear to the shaft 187. Should it be desired to render both of the cutters 150 inoperative with respect to their bodily oscillating movement, all that is necessary is to 5 shift both of the clutches 188 so as to unlock both of the gears 187. These operations may be accomplished without affecting in any manner the operation of the remaining portion of the mechanism.

10 An adjustable connection is provided between the gear 179 and the arm 152, and embodies a member 191 (Figs. 1, 11 and 24) which is provided adjacent one extremity with a lateral projecting portion 192 (Fig. 11) having a bearing in a member 193 connected with the arm 152. To the free end of the member 191 are connected rods 194 (Fig. 24) which are threaded by one extremity into the member 191, and jam-nuts 195 (Fig. 20 11) are provided for holding these parts against accidental disengagement. The free extremities of these rods 194 pass loosely through a bearing member 196 (Figs. 11 and 24) and are threaded to receive nuts or 25 collars 197, 198 by means of which the bearing member may be adjusted with respect to the rods 194 and held in its adjusted position. A member 199 (Figs. 11, 25 and 26) is adjustably supported in guides 200 carried by the 30 gear 179, and this gear is preferably hollow, so that the guides 200 and the member 199 may be disposed within the hollow portion. This member 199 is provided with a trunnion or axle 201 which projects laterally beyond the face of the gear 179 and has a bearing in the bearing member 196, and a fastening device 202 is provided for securing these parts against accidental disengagement. Thus it will be seen that with this connection 35 between the gear 179 and the arm 152, at each revolution of the gear, the arm will be rocked about its point of pivotal support and thereby oscillate the cutters 150. This connection also serves as a means for supporting the forward end of the arm and in 40 order to vary the extent or degree of oscillating movement of the cutters 150, from a point which remains constant and which point is the lowest point the cutters will 45 assume with respect to the main supporting frame, the connection is made adjustable as above described, and the member 199 is adapted to be adjusted in the guide 200. In order to secure the adjustment of this member 199, in its guides, an adjusting screw 50 203 is provided which has a threaded extremity 204 (Figs. 11 and 26) having engagement with the member 199 while the extremities of the screw have engagement 55 with the flange or arm of the gear 179. One extremity of this screw is shaped as at 205 so as to receive an adjusting wrench or tool by means of which the screw may be rotated, and as the screw is rotated, the threaded portion thereof will cause the member

199 to move in the guide-ways 200 in either direction according to the direction of rotation of the screw. The screw 203 and the portion 205 thereof are located behind the member 191 and in order to permit access 70 to the portion 205 of the screw by means of a wrench, or tool, the member 191 is provided with an aperture or opening 206 through which the tool may be inserted into engagement with the portion 205. In order 75 to vary the degree of movement of the arm 152 from the degree of movement which will be imparted to it with the parts in the position as shown in Fig. 24, and without varying the lowest point of movement of the 80 arm 152, it is first necessary to loosen the nuts or collars 197, 198 according to the direction of adjustment desired, that is, for a longer or shorter oscillating movement. After which, and assuming that the nuts or 85 collars 197 are loosened, the screw 203 is adjusted so as to move the member 199 toward the axis of rotation of the gear 179 and then the nuts or collars 198 are adjusted into engagement with the bearing member 196, 90 after which the nuts or collars 197 may be also adjusted into engagement with the member 196 to hold the parts in their adjusted positions. As shown in Fig. 11, the downward movement of the member 199 is 95 limited by the inner surface of the hollow gear 179.

Thus it will be manifest that with this adjustment, the arm 152 will not be lowered below the same point although the degree 100 of oscillating movement may be varied. This is necessary, that is, the arms must always stop at the same lowest point because if the arm is lowered below this point by the adjustment just described, the cutters 150 105 would contact with a portion of the mechanism, that is, the portion beneath the cutters which would be objectionable for obvious reasons. The front of the shoe 134 is curved, as shown, in order to conform to the contour 110 of the cutters and is spaced from the cutting tools 151, as shown more clearly in Fig. 1 so as not to be engaged thereby.

The arms 152 may also be supported by adjustable stops which may be provided, if 115 desired, and comprise adjusting screws 207 (see particularly Figs. 1, 6 and 16) adjustably connected with suitable supports 208 which latter may be formed on any suitable support, preferably the uprights 148, and 120 the screws 207 and supports 208 are located below the arms 152 and in such positions that the screws may be adjusted so that the arms will engage and rest upon the extremities thereof when the arms are in their low- 125 ermost positions as shown in Fig. 1.

The cutters thus far described operate upon the material to be mined to make horizontal cuts or kerfs in the wall thereof together with spaced upright or vertical cuts 130

or kerfs, and in order to remove or dislodge the material between the cuts or kerfs, breaking down mechanism is provided, and this mechanism operates upon the material 5 to dislodge the same.

In the present exemplification of this invention, the breaking down means comprises tools, designated by the reference numeral 209, in Fig. 38, preferably four in number, 10 although any desired number of tools may be employed, and these tools 209 are provided at their forward extremities with sockets 210 for the reception of pick members 211 which latter strike the material to 15 dislodge the same. The tools are supported by a member or cross-bar 212 which in turn is supported between spaced arms 213, (see particularly Figs. 1 to 4, 11, 30 and 33), and which arms are (Figs. 4 and 33) preferably 20 of channel formation. The arms 213 are each provided at one extremity with a depending portion 214, preferably in the form of an upright, which uprights are pivotally mounted adjacent their lower extremities 25 upon the frame 105, and for this purpose, the portions 214 are provided with a boss 215 (see particularly Figs. 31 and 33), which enters a suitable bearing in the frame 105. The arms 213 are each provided with an ex- 30 tension 216, also preferably in the form of a channel iron (see particularly Figs. 1, 3 and 11) which enter the extremities of the arms 213 and with which the ends of the member or cross-bar 212 have direct engagement, and 35 these parts are secured together at these points in any desired or suitable manner. These extensions form portions of the arms 213 and their forward extremities terminate adjacent the cutters 150 as shown. Arms 40 ranged between the rear extremities of the arms 213, is a spacing member 217 (see particularly Figs. 30, 31 and 32) which is preferably provided with shoulders 218 that engage the edges of the channel irons with 45 their extremities overlapping said edges so that fastening devices 219 will secure the plate and the arms together.

As the construction and operation of each of the tools is the same, the specific description of one will apply equally as well to them all. The tool 209 (see particularly Figs. 3, 4, 33 and 38) is provided with a stem 220 at 50 one extremity of which is arranged the socket 210, (Fig. 38) and this stem is of a length to pass through the cross-bar or member 212 to project some distance to the rear thereof and terminate adjacent the portions 213 of the arms. The forward extremities of the tools are supported in any suitable manner, but preferably by means of sectional bearings or boxes 221 (see particularly Figs. 3 and 38) which are arranged at the extremities of the portions 216 and between two cross-bars 222 55 which extend across and rest upon the edges

of the portions 216. These boxes or bearings serve as guides, through which the socket portions 210 of the tools pass, and the boxes and bars 222 are secured in position by suitable fastening devices 223. The body of the 70 tool is provided with a shoulder 224 against which one end of an elastic member 225 rests, and the other extremity of this elastic member has engagement with the cross-bar or member 212 and the elastic member tends 75 normally to project the picks 211 beyond the extremity of the portions 216 of the arms. The cross-bars 222 and the cross-bar or member 212 are fixed with respect to each other so that when the stem 220 of the tool is 80 drawn through the cross-bar or member 212, toward the right in Fig. 38, the elastic member 225 will be compressed, and when the stem is released, the tension thus created upon the elastic member 225 will project 85 the picks 211 forcibly into engagement with the wall of the material being operated upon.

The tool is adapted to be drawn back to create a tension on the elastic member 225 and automatically released after the tension 90 has been created thereon by mechanism which will now be described. Slidably mounted upon the plate 217 is a cross-head 226 which is provided with openings 227 therethrough, (see also Fig. 39) through 95 which the free extremities of the stems 220 of the tools are adapted to project, and pivotally mounted upon the cross-head, adjacent each of the openings 227 is a dog 228 (see particularly Figs. 34 and 35). One extremity 229 of this dog projects into the path of movement of a stop 230, preferably in the form of an anti-friction roller mounted in a grooved portion 230^a (see also Fig. 42) in the extremities of the stem, so that when 100 the extremity of the stem enters the openings 227, the stop or roller 230 will engage the extremity 229 of the dog and rock the same to permit the stop to pass, and when the stop has passed to the position shown in 105 Fig. 38, the extremity 229 of the dog will pass to the other side of the stop or roller and thereby connect the cross-head 226 with the stem 220, so that when the cross-head is moved the stem will be moved thereby. This dog 228 is adapted to be automatically rocked into and out of positions where it will engage and disengage the stop or rollers 230 by 110 means of spaced stops 231, 232, between which another extension 233 projects. These 115 stops are arranged adjacent the limits of the movement of the cross-head so that when the extension 233 of the dog engages one of the stops, the stop 231, a further movement of the cross-head in the same direction will cause the dog to be rocked about its point of pivotal support, to move the extension 229 out of engagement with the stop 230 and thereby release the tool so that the tension 120 which has been created upon the spring 225 110

5 by movement of the cross-head in this direction, will forcibly project the tool to strike the material operated upon. When the cross-head 226 reaches the limit of its movement in the opposite direction, the extension 233 on the dog 228, will engage the stop 232, and the dog will be rocked into position that the extension 229 will engage the stop or rollers 230, so that on the return movement of 10 the cross-head the stem will be retracted thereby. If desired, the stop 231 may be an adjustable stop, preferably in the form of a screw or bolt, as shown in Fig. 33, so that the time at which the extension 233 will engage 15 the stop 231, may be varied. The stops 231 may be supported in any desired or suitable manner, preferably by means of an upright portion 234 on the plate 217 and in order to reinforce this upright portion, tie 20 rods 235 may be provided, which pass through the cross-bar member 212 as shown more clearly in Fig. 38, and also through the upright portion 234 on the plate 217.

Thus it will be manifest that when the 25 cross-head 226 is reciprocated, its movement in one direction will cause the dog 228 to lock the tool thereto so that the movement of the cross-head in the opposite direction will draw the tool back to create a tension 30 on the spring 225, and just as the cross-head reaches the limit of its return movement, the dog will be tripped to release the tool.

The diameter of the stem 220 and the elastic member 225 is such that the elastic member will pass into the opening in the bearing members or blocks 221, (Fig. 10) so that the forward movement of the tool will not be interfered with.

40 The cross-head 226 is reciprocated in the present form of the invention, by means of oscillating members 236 (see particularly Figs. 31, 4, 33, 36 and 37) which are pivotally supported adjacent one extremity, and by the upright portion 214 of the arms 45 213 by means of an axle 237, and the portion 214 is preferably provided with a peripheral flange 238 to form a space within which the oscillating members 236 move. Each of these members 236 is provided adjacent its other extremity with a trunnion 239 projecting laterally therefrom, and to which is pivotally connected one extremity of a link 240. The other extremities of these links, and which links are located on opposite sides of the cross-heads 226, are pivotally connected as 240^a with the cross-head, so that when the members 236 are oscillated, the links will cause the cross-head to be reciprocated, and the members 236 oscillate to 55 such an extent that the extension 233 on the dog 228 will be moved into and out of engagement with the respective stops 231, 232. In order to hold the dog 228 in the respective positions into which it is adjusted by 60 the stops 231, 232, there is provided an elas-

tic member, such as a spring, preferably in the form of a leaf spring 241 (see particularly Figs. 4 and 33) which co-operates with a shouldered portion 242 (see also Figs. 34 and 35), on the dog. This shouldered portion is provided with a face 243 with which the spring 241 engages to hold the dog in one position, and a portion 244 with which the spring has engagement to hold the dog in the other of its positions. The tension of 70 this spring is such that it will normally hold the dog in its adjusted positions, but will yield under pressure, that is, when the dog is shifted by the stops 231, 232, to permit the dog to be moved into one or the other of 75 its positions.

Each of the members 236 is oscillated by means of a crank arm 245 arranged between the members 236 and the adjacent face of the portion 214. This crank arm is provided with a pin 246 (Fig. 36) projecting into a slot or guideway 247 in the member 236, and a sliding bearing 248 (Fig. 37) may be provided on this pin 246, so that when the crank is rotated, the sliding bearing will travel in the guide-way 247 in the member 236 and thereby oscillate the member about its point of pivotal support. The crank 245 is provided with an axle 249 which is journaled in a bearing 250 in the upright 90 214 (Fig. 31). In order to house the crank and the member 236, a plate 251 is provided which engages the edges of the flange 238 and is secured in position in any suitable manner.

Motion is imparted to the crank arm 245 from the gear 111 by means of a gear 252 which is loosely mounted upon the axle 237 (Fig. 31), and this gear 252 meshes with another gear 253 connected with the axle 105 249 of the crank 245. The free extremities of the axles 116, 237, (see particularly Figs. 2, 31 and 78) are journaled in a plate or member 254 which is secured by suitable fastening devices 255 (Figs. 2 and 31) to the 110 portion 214 of the arms 213, and a second plate or member 255^a is secured by suitable fastening devices 256 with the frame member 105 and is provided with an opening 257 for the reception of a boss or projection 258 115 on the plate 254. The plate or member 254 may be provided with an oil cup 259 having a suitable closure, and a similar oil cup 260 may be provided in the member 214.

In order to insure the proper operation 120 of the cross-head 226, that is, so that both ends thereof will operate uniformly, and in order to avoid the necessity of adjusting all of the gears, the gear 253 (Figs. 2, 31 and 76) which is connected with one of the 125 cranks 245, is connected to the axle 249 thereof by means of an adjustable connection whereby the gear may be adjusted with respect to the axle to position the teeth of the gear, (Fig. 76) so that both of the gears 130

253 will be in proper position with respect to each other and with respect to the teeth of the meshing gear. In order to accomplish this, one of the gears 253 is loosely mounted 5 upon the bearing 250, and keyed to the shaft within the hub of the gear 253, is a support 261 (see particularly Figs. 75, 76, 77 and 79) which is provided with slotted portions 262 into which slots project one extremity 263 10 of bolts 264. These bolts are pivotally supported by means of pivot pins 265 passing transversely through the ends 263 thereof, and which bolts have engagement with the walls of the slot of the support 261. The 15 gear 253 is provided with a projecting portion 266 having slots 267 in opposite sides thereof, and the projecting portion 266 of the gear receives the support 261, and the free extremities of the bolts 264 project 20 through the slots 267 and are provided with threads. Collars 269 are provided on the bolts which engage under shoulders 270 on the extension 266 of the gear 253, and nuts 271 are mounted on the threaded extremities 25 of the bolts for forcing the collars 269 in engagement with the shoulders 270. Thus it will be manifest that by adjusting the nuts or collars 271, the gear 253 may be rotated with respect to the axle 249 and the support 261, which latter is secured to the axle to properly position the teeth of the gear 253, so that the teeth of this gear may be brought into register with the teeth of the gear 253 on the opposite side of the machine. 30 The breaking down means or pick mechanism is counterbalanced on its pivot by mechanism which will now be described.

Arranged on the side of the points of pivotal support of the cutters opposite to the 40 side on which the tool is arranged and slidably mounted in guide-ways 272 (see particularly Figs. 4, 7, and 31), is a slide 273 with which projecting ears or lugs 274 on the portion 214 of the tool supporting frame, 45 have engagement. A cross-bar 275 cooperates with the slide 273 and is spaced therefrom, and between the cross-bar and slide elastic members 276 are disposed, any number of which may be employed and are preferably in the form of spiral compression 50 springs. These elastic members are supported in position by means of bars or rods 277 (Fig. 7) which are connected by one extremity to one of the members 273 or 275, 55 preferably the slide 273 and pass loosely through the other of the members, and these bars or rods also pass through the elastic members 276. The bar 275 is held in position with respect to the slide 273 by means 60 of the springs 276 limited by a rod or bolt 278, which passes loosely through the bar 275 (Fig. 7) so that its headed extremity 279 will engage the bar 275. The free extremity of this rod 278 is preferably threaded as at 280, and passes loosely through an

ear or projection 281 on the motor frame 45, and a nut or collar 282 is connected to the threaded extremity 280 of the rod 278 for holding the parts against disengagement. The bar 275 is held spaced from the slide 70 273 by means of this bolt or rod 278, a sufficient distance that the elastic members 276 will be normally held under compression, and this stored up energy exerted upon the slide 273 which engages the projections 75 274 on the frame of the pick or breaking down means, will tend to force the frame, about its point of pivotal support in a direction opposed to the direction of movement which is imparted thereto by the weight of the 80 pick or breaking down mechanism. These elastic members 276, however, are not of sufficient strength to entirely counterbalance the structure, but are of sufficient strength to assist in supporting the pick or tool and 85 will permit the frame which supports the breaking down means, to drop or move in such a direction that the pick or tool 211, when the machine is not in operation, or when the pick is not otherwise held supported, to move toward and assume a position in proximity to the bottom or base of the machine. Obviously, the tension of the elastic members 276 may be varied by adjusting the nut or collar 282 upon the rod 278, and 90 the bar 275 may be slidably supported upon a bearing portion 283 on the frame 14 (Fig. 4).

The frame of the breaking down means or pick mechanism is adapted to be raised 100 so as to elevate the pick against the weight of the structure by means of the motion of the gears 111, 252 and 253, in a manner which will now be described. Assuming the tool or breaking down means to be in the 105 position shown in Figs. 1, 2, 3, 4 and 33, the operation of raising or feeding the tool upwardly is as follows: When the gears 111 are rotated in a clockwise direction, which is the direction of rotation of this 110 gear, they will operate upon the gears 252, and they will in turn operate upon the gears 253. The rotation of these gears 253 will rotate the crank arms 245 (see also Fig. 31), and these crank arms will, through the medium of the oscillating members 236 and the links 240, first move the cross-head 226 forwardly to cause the extremities 229 of the dogs 228 to engage the rollers or projections 230 on the stems 220 of the tool to retract 120 them, and thereby create a compression upon the elastic members 225. The gears 252 and 253 will rotate freely with respect to the portion 214 of the supporting frame of the breaking down tools, until sufficient compression has been created upon the elastic members 225 to create a resistance to the 125 gears 253 and 252. As soon as this resistance between the gears 253 and 252 is sufficient to overcome the resistance at the point 130

of engagement of the gears 252 with the gears 111, the gears 252 will be held against rotation with respect to the supporting frame, and will serve as a lock so to speak for the gears 252. A further rotation of the gears 111 will then cause the gears 252 to be moved or "walked" bodily about the gears 111, and this movement of the gears 252 assisted by the elastic members 276, will 5 move the entire supporting structure of the breaking down means about its point of pivotal support which will have the effect of raising the forward ends of the tools or breaking down means to feed them upwardly. This feeding or raising movement of the breaking down means, will continue as long as the resistance at the point of engagement of the gears 252 and 253 is greater than the resistance between the point 10 of engagement of the gears 252 and 111. In order therefore, to prevent this feeding movement of the breaking down means after the latter has been adjusted a sufficient distance so that the breaking down means will 15 operate upon a new portion of the material to be mined, it is necessary to provide means for overcoming the resistance between the gears 252 and 253. Mechanism for accomplishing this result will now be described, 20 reference being had more particularly to Figs. 2, 4, 31, 54, 56, 59 and 65. Supported by the portion 214 of the frame for movement therewith, is a segment 284 which is provided with a laterally projecting flange 285 having spaced teeth 286 projecting preferably from the lower face thereof, and this flange projects and moves over an extending portion of the frame 105 as shown more 25 clearly in Figs. 2 and 54. Slidably mounted 30 upon the frame 105 to project beyond the frame and to enter the recess between the teeth 286 of the segment, is a ratchet dog 287 (see particularly Figs. 54, 59 and 60). The extremity of this dog which projects 35 into the spaces between the teeth 286 is beveled or inclined as at 288 to permit the dog to be shifted by the engagement of the teeth 286 with the inclined face 288 when the segment is moved in one direction, and to 40 lock the segment against movement in the opposite direction. Slidably mounted upon the dog 287 is a supplemental ratchet dog 289 which is connected with the dog 287 in any suitable manner, preferably by means of 45 a pin and slot connection 290 and 291, so that the supplemental dog 289 will move with the dog 287 and will also be adapted for independent movement with respect thereto. The extremity of this supplemental 50 dog 289 is also adapted to enter the spaces between the teeth 286, and the combined width of the extremities of the dogs 287, 289 is such, that they will substantially fill the spaces between the teeth. The supplemental 55 dog is also provided with an inclined or bevelled face 292 for the same purpose as the face 288 of the dog 287, and these inclined faces 288, 292 are opposed to each other, as shown more clearly in Fig. 59, so that one of the dogs will be shifted by the teeth 286 60 when the segment moves in one direction, and the other will be shifted by the teeth when the segment moves in the opposite direction. An elastic connection 293 is provided between the dogs 287, 289, and tends 65 normally to project the dog 289 as shown, and to hold the dog 289 projected when the extremity of the dog 287 is retracted. The dog 287 is shifted by means of a lever designated generally by the reference numeral 70 294 pivoted intermediate its ends as at 295 (Fig. 54) and with one end 296 connected with the dog 287, preferably by projecting into a recess 297 in the dog so that when the lever 294 is rocked about its point of 75 pivotal support, the dog 287 will be correspondingly shifted. The other extremity 298 of the lever 294 projects into the path of movement of a tappet 299 which is connected with a gear 300 (see particularly 80 Figs. 2 and 54), and which gear is rotatably mounted upon the frame 105 and meshes with the gear 111. The axle 301 of this gear 300, has a bearing in the frame 105 and also in the plate or member 255, as shown more 85 clearly in Figs. 2 and 56. An elastic member 302 is provided which tends normally to move the extremity 298 of the lever 294 into the path of movement of the tappet 299 and also operates upon the end 296 of the 90 lever 294 to move it in a direction to project the extremity of the dog 287 so as to enter the recesses between the teeth 286 of the segment 284, but will yield to permit the extremity of the dog 287 to be shifted by 95 the engagement of one of the teeth 286 with the beveled face 288 thereof when the segment moves in one direction. 100

In order to hold the supplemental dog 289 projected to lock the segment 284 against 110 return movement when the dog 287 is retracted, a latch or member, designated generally by the reference numeral 303, (see particularly Figs. 54 and 59) is pivotally supported intermediate its ends as at 304. 115 One extremity 305 of this latch 303 is adapted to be moved by means of an elastic member 306 into the path of the return movement of the supplemental dog 289, that is, into a position that it will engage the end 120 of this supplemental ratchet dog and hold the latter against return movement. This latch also serves as a means for temporarily locking the ratchet dog 287 in its retracted position after the tappet 299 has passed out 125 of engagement with the extremity 298 of the lever 294 so as to permit the segment to be moved in a direction to elevate the breaking down tool. This is accomplished by means of the extremity 307 of the latch, 130

which is adapted to be moved against a face 308 of the lever by the elastic member 306, when the latter is shifted by the tappet 299 and will hold the lever in this position, and 5 consequently the dog 287 in a retracted position until the latch 303 is shifted against the tension of the elastic member 306. This shifting movement of the latch 303 to release the lever 294, is accomplished by the 10 shifting movement of the supplemental ratchet dog 289, which movement will be imparted thereto by the tooth 286 of the segment 284 engaging the inclined face 292 of the supplemental dog when the segment 15 is moved, to elevate the breaking down means. The latch 303 will be held in its shifted or inactive position by means of another portion of its extremity 307 engaging a portion of the lever 294.

20 The automatic operation of feeding or raising the breaking down means briefly stated, is as follows:

As has already been stated, the gears 111, 252 and 253, under certain conditions, will 25 swing the supporting frame of the breaking down means or tools about its point of pivotal support in a direction to raise the operating end of the breaking down means so long as the resistance between the gears 252 30 and 253 is greater than the resistance between the gears 111, 252. The greater resistance between these gears, in order to unlock the gears and to permit them to rotate about their axes without elevating or feeding 35 the breaking down means, is accomplished through the mechanism which has just been described. Assuming the parts to be in the position shown in Figs. 54 and 59, and with the extremities of the dog 287 and 40 of the supplemental ratchet dog 289 projected into one of the recesses between two of the teeth 286 of the segment 284, it will be manifest that the supporting frame of the breaking down means or pick, will be locked 45 against movement about its point of pivotal support in either direction, and therefore the gears 252, 253 will be unlocked inasmuch as this locking of the supporting frame will overcome the friction between the gears 252, 50 253, and the gear 252 will then rotate. During the rotation of the gears 111 in the direction indicated by the arrow in Fig. 54, which is the constant direction of rotation of the gears 111, the gears 300 will be rotated in the direction indicated by the arrow in said figure, and the supporting frame of the breaking down means will be locked and maintained locked in the manner just described, until the tappet 299 engages the extremity 298 of the lever 294. This tappet 55 299 will then rock the lever 294 against the tension of the elastic member 302, which rocking movement will withdraw the ratchet dog 287 to such an extent that its extremity 60 will pass out of the recess between the teeth 65

286 of the segment 284. At the same time, the movement of the lever 294 will permit the elastic member 306 to operate upon the latch 303 in the manner already described to lock the lever 294 against return movement, and also to lock the supplemental ratchet dog 289 against movement. When the segment 284 is thus released, the resistance between the gears 253, 252, again 70 becomes greater than the resistance between the gear 252 and the gear 111, with the result that the supporting frame of the breaking down mechanism will again be moved about its pivot in a direction to elevate the forward end of the breaking down means 75 and to lower the segment. This movement of the supporting frame will continue until one of the teeth 286 of the segment 284 engages the inclined face 292 of the supplemental ratchet dog 289. A further movement of the frame in the same direction, will 80 cause the tooth of the segment to ride over the face 292 of the supplemental ratchet dog to force the latter in a direction that its extremity will be withdrawn from the recess between the teeth. This movement of the supplemental ratchet dog will shift the latch 303 against the tension of the elastic member 306, so as to unlock the lever 294, and when unlocked, the elastic member 302 will 85 shift the lever to move the ratchet dog 287 in a direction to project its extremity so that it will enter the recess between the next two of the teeth of the segment. By the time the lever 294 has been unlocked by the shifting of the supplemental dog 289, the recess between the next two teeth 286 of the segment will assume a position to receive the extremity of the dog 287, and the frame will 90 then be locked against movement about its pivot. As soon as the tooth has passed off of the inclined face 292 of the supplemental ratchet dog 289, the elastic member 293 will shift the supplemental ratchet dog to project its extremity into the same recess into 95 which the extremity of the dog 287 has just been projected. This intermittent feeding or elevating of the breaking down means 100 may be continued or repeated as long as desired.

The raising and lowering or the feeding of the breaking down means, may also be controlled at the will of the operator, and for this purpose there is provided an operating lever 309 which is connected with the 105 lever 294, as shown in Figs. 2 and 54, by means of which the lever 294 may be shifted at will. When it is desired to permit the breaking down means to be raised or adjusted to a predetermined height quickly and 110 without waiting for the intermittent advancement or feeding of the breaking down means, the lever 309 is shifted a distance sufficient to withdraw the extremity of the ratchet dog 287, and when the tool has been 115 120 125 130

- properly positioned, the lever may be released to permit the parts to resume their positions for automatically adjusting the breaking down means.
- 5 After the breaking down means has reached the highest position, and it is desired to lower it, it is necessary to overcome the tendency of the gearing 111, 252, and 253 to rock the supporting frame about its pivot.
- 10 It has already been stated that by reason of the tension created upon the elastic members 225 or the resistance to the gear 253 which is caused by this tension, the supporting frame will be rocked about its pivot.
- 15 through the operation of the gears 111. In order to overcome this tendency to raise the breaking down means, it is necessary to prevent a tension from being created upon the elastic member 225, but inasmuch as the
- 20 cross-head 226 reciprocates upon every revolution of the crank arm 245, the dog 228 will be positioned by the engagement of the extension 233 with the stops 232 to position the extension 229 to engage the stop or roller 230. When the extension 233 engages the stop 231, the dog 228 will be rocked in the opposite direction to release the stem 220 of the tool as has already been stated. In order to prevent the extensions 233 from engaging the stops 232 when the cross-head moves in the other direction, these stops 232 are shifted so that the extensions 233 will not engage the stops, and consequently the extension 229 will not engage the stops or
- 25 rollers 230, which will cause the cross-head to reciprocate without retracting the tools. This therefore, will not create a tension upon the elastic members 225 and there will not be sufficient resistance created between the
- 30 gears 252 and 253, to raise or feed the breaking down means, and inasmuch as the breaking down means and supporting structure are of a weight to slightly overcome the strength of the elastic members 276, the forward ex-
- 35 tremities of the picks or breaking down means, will drop upon the actuation of the manual lever 309 sufficiently to move the pin 290 to the left (Fig. 54) and withdraw both latches 287 and 289, the elastic means 276 then acting in the nature of a cushion. Any suitable means may be provided for shifting the stops 232, but a simple and efficient means will now be described. The stops 232 are formed upon a cross-bar or member 310,
- 40 which latter extends transversely of the stems 220 and is supported in position preferably by resting upon the tie-rods 235 (see particularly Figs. 32, 33, 38 and 40), and is held in position by means of suitable clips 311 (Fig. 32) which latter are fastened by suitable U bolts 312. The clips 311 are preferably offset as shown with respect to a guide-way in which the cross-bar 310 is adapted to slide. This cross-bar 310 is
- 45 adapted to be shifted by means of a bar or

rod 313 having a handle 314 arranged in a convenient position for the operator, and the rod is supported by suitable bearings 315, 316 (see Figs. 3 and 4). The cross-bar 310 is provided with an inclined guide-way 317 (Fig. 32) into which a projection 318 on the rod 313 projects, so that when the rod 313 is shifted in its bearings by the handle 314, the projection 318 will engage the walls of the guide-way and will shove the bar 310 in its bearings in one direction or the other according to the direction of movement of the rod 313. When it is desired to shift the stops 232 from the position shown in Fig. 32, all that is necessary is to pull the rod 313 longitudinally, and when it is desired to reposition the stop 232, all that is necessary is to shift the rod 313 in the opposite direction. When the stops 232 are thus moved out of the path of movement of the dogs on the cross-head, as has been before stated, the cross-head will reciprocate without operating the picks. In order to throw the picks out of operation or hold them retracted, pivoted catches 319 are provided on opposite sides of the stems 220 and are pivotally supported in suitable bearings 320 (see also Figs. 17, 18, 19) carried by the extensions 216 of the arms 213 and are connected by means of links 321 for operation in unison. The sockets 210 of the picks are provided with shoulders 322, with which these catches 319 coöperate, that is, they are adapted to be engaged by the edges of the catches when the picks are retracted and will hold the picks in this position. These catches are adjusted by means of the rod 313 with which they are connected by means of extensions 323 (see Figs. 17 and 38) to which extensions is pivotally connected a sleeve 324 through which the rod 313 passes. The bearing 316 for the rod is arranged adjacent the sleeve 324, and an elastic member 325 in the form of a coil spring is disposed between the sleeve and the bearing 316, and tends normally to exert its tension upon the sleeve to shift the catches 319 into the positions shown in Figs. 3 and 38 to unlock the tools. The extremity of the rod 313 passes through and for some distance beyond the sleeve 324 and is provided with a head 326. When the rod 313 is shifted longitudinally, a sufficient distance to cause the head 326 to engage the sleeve 324, the catches 319 will be shifted into positions to engage the shoulders 322 of the sockets 210, and the extremities of the catches will ride over the elastic members 225, and when the rod is shifted in the opposite direction to move the head 326 away from the sleeve 324, the elastic member 325 will return the catches. Should it be desired to shift only the stops 232, the rod 313 is drawn back only a sufficient distance to accomplish this end, and the head 326 will not engage the sleeve 324.

130

Should it, however, be desired to shift both the stops 232 and the catches 319 so that the latter will lock the tools in their retracted positions, the rod 313 is drawn upon sufficiently to cause the head 326 to engage the sleeve 324 and shift the catches. After the catches have been shifted so that the shoulders 322 of the tools will engage the edges of the catches, the catches and the rod 313 will be held in their adjusted positions by the pressure of the shoulders 322 exerted on the edges of the catches by the elastic members 225.

In order to control the descent of the breaking down means, band brakes 327 are provided for each of the segments 284, one extremity of each of which is secured to a suitable fixed support 328 (see Fig. 2), by means of a fastening device 329 (Fig. 32) so that the brakes will engage and rest upon the flanged portions 285 (Fig. 65). The free extremities of these brakes are connected to a shaft 330, through the medium of eccentric connections 331, 332, (Fig. 59) and this shaft extends across the machine and is journaled in the frame 105. The shaft is provided with operating handles 333, (Fig. 2) one of which is located on each side of the machine whereby the brakes may be controlled from either side of the machine.

When it is desired to lower the tools or breaking down means, it is first necessary to render the dogs 228 inoperative by shifting the stops 310 (Fig. 32) in the manner already described, and then the ratchet dogs 287, 289 (Fig. 54) must be shifted into inoperative positions so that they will not enter the space between the teeth 286 of the segment 284. This is accomplished by the means of the handle 309, shown more clearly in Fig. 54, which latter is shifted to such an extent that the dog 287 will be moved so that the pin 290 will engage the end of the slot 291 as will be understood. Thus released, the breaking down means will automatically drop, and the extent of movement and the rapidity with which it is lowered, may be controlled by the band brakes 327.

While in the present exemplification of this invention, there is shown only one feeding mechanism for elevating the breaking down means, it is to be understood that if desired, the mechanism may be duplicated on the opposite side of the machine, and in this event the shaft 295 will extend across the machine and with which is connected a lever similar to the lever 294 (see Figs. 54 and 56), another lever or handle 309 may then be provided on the opposite side of the machine so that the mechanism may be controlled from either side of the machine.

As the material to be mined is cut and dislodged or broken down by the breaking down means, it will drop upon the platform 65 at the forward end of the endless conveyer

to be carried by said conveyer to the discharge end thereof, from which end it is delivered to a supplemental or swinging conveyer which is supported upon the frame 14 for movement therewith, so that it will be advanced and retracted with the sliding structure. This supplemental conveyer (see particularly Figs. 2, 4, 43, 44 and 49) is provided with a hopper 334 which is located beneath the discharge end of the conveyer to receive the material as it passes from the conveyer 90. This supplemental or swinging conveyer is mounted upon the frame 14 preferably by one extremity, and is adapted to be rotated about a vertical axis 80 with respect to the frame 14. In order to accomplish this, there is provided what may be termed a supporting plate 335 (Fig. 44) which is connected with the frame and is provided with a recessed portion 336 into which projects a cylindrical portion 337 depending from the bottom 338 of the supplemental conveyer, and mounted upon the cylindrical portion to move upon the base or bottom of the recess, are anti-friction rollers 339 which are journaled in suitable bearings. A plate 340 is also provided which serves as a closure for the recess 336 and also projects over the anti-friction rollers 339. This plate 340 is itself provided with an aperture 95 through which the cylindrical portion 337 projects and is secured in position in any desired or suitable manner. Thus it will be manifest that the supplemental conveyer may be rotated upon the vertical axis thus formed. The supplemental conveyer frame is provided with arms or extensions 341 (Fig. 49) which project laterally beyond the main supporting frame of the machine as well as beyond the sliding frame 14, and these arms 341 form a support for the runway or frame 342 of the conveyer. This supplemental conveyer frame is provided with a section 343 which is pivotally connected as at 344 with the main portion of the frame. The forward portion of the conveyer frame adjacent the hopper, preferably inclines upwardly as shown in Fig. 49, and is supported by means of suitable uprights 345 mounted upon the extensions 341, and the free extremity of the pivoted section of the conveyer frame is supported by means of an adjustable support embodying sections 346, 347 (see also Fig. 70) one of which sections, 346, is pivotally connected as at 348 with the extensions 341, and the other section 347 is pivotally connected as at 349 with the section 343, and a turnbutton construction embodying a hand wheel 350 and a threaded shaft 351 connects the sections 346, 347. The shaft 351 has threaded engagement with the sections, whereby the adjustment of the hand wheel 350 will separate the sections or draw them together to raise or lower the free extremity of the pivoted 110

115

120

125

130

section 343 of the conveyer frame. Endless flexible members 352 (Fig. 50) are provided in the conveyer frame and pass over sprocket wheels 353 (Fig. 44) at one end of the 5 frame, and similar sprocket wheels 354 (Figs. 49, 50 and 51) at the other end of the frame, and these flexible members are connected by cross-bars or flights 355. The 10 conveyer frame is provided with a supporting plate or member 356 which extends substantially the entire length of the inclined portion of the frame, and also a supporting plate 357 which extends substantially the entire length of the section 343 of the frame. 15 One of the runs of the endless conveyer thus formed, travels about or rests upon the supporting plates or members 356, 357, while the other run of the conveyer passes below the plates or members, and the conveyer is 20 of such a size that the lower run will have some slack. The sprocket wheels 354 (see Figs. 49 and 51) are preferably mounted in adjustable bearings 358 for taking up some of the slack of the conveyer. Motion is imparted to these endless flexible members, 25 preferably by means of a sprocket wheel 359 which is journaled in suitable bearings 360 in the support 345, and the sprocket wheels are preferably located below the lower run 30 so that the run of the conveyer will pass over the top of the sprocket wheels to rest thereon and so that the run extending over a mine car will be held taut. This driving arrangement is claimed in my co-pending 35 application, Serial No. 186,118, filed August 14, 1917, loading machine. The sprocket wheels are connected by means of a shaft 361 (see particularly Fig. 69) with which shaft is connected a gear wheel 362 for rotation therewith. This gear wheel receives its 40 motion from a gear 363 which meshes therewith and which latter gear is connected with an upright shaft 364 journaled in suitable bearings 365 in the support 345. Connected 45 with the shaft 364, is a sprocket wheel 366 over which an endless flexible member 367 passes. The endless member 367 also passes over another sprocket 368 (Fig. 44) which latter sprocket wheel is connected with an 50 upright shaft 369 journaled in a suitable bearing, preferably in the cylindrical depending portion 337 of the conveyer, as shown more clearly in Figs. 4 and 44. The shaft 369 receives its motion by means of a 55 gear 370 which is connected with the shaft, and with which gear 370, a gear 371 carried by the motor shaft 44 meshes (Figs. 9 and 44), and this gear 371 is located on the side of the motor casing 45 opposite to the side 60 on which the gear 46 is located, as shown more clearly in Fig. 4. Thus it will be seen that when the motor is operated, the gear 371 will be rotated and this will in turn rotate the shaft 369 to impart motion to the 65 sprocket chain 367. This sprocket chain will in turn rotate the gear 366 (Fig. 49), the upright shaft 364, and the gear 363, which latter will rotate the gear 362 and the shaft 361, and consequently the sprockets 359. All of the supplemental conveyer structure 70 above described is mounted upon the sliding frame 14 so that the hopper or inlet end of the supplemental conveyer will always be maintained below the outlet end of the main conveyer during the reciprocating 75 movement of the sliding structure, and the gears will always be maintained in mesh, while at the same time, the supplemental conveyer may be swung about its vertical axis. If desired, the section 343 of the supplemental conveyer frame may be provided 80 with a bottom 372 (Fig. 49) which serves as a support for the lower run of the conveyer, and a ledge or extension 373 may be provided at the outlet end of the section 85 343 of the supplemental conveyer frame, as shown more clearly in Figs. 49 and 51. The sides of the supplemental conveyer frame are preferably provided with angle irons 374 (Fig. 50), beneath which the runs of the 90 endless flexible members pass so that the latter will be protected thereby, and the sides of the conveyer frame are preferably inclined as shown, so as to direct the material on to the conveyer. The plate 340 may 95 be provided with reinforcing or strengthening ribs or projections 375 (Figs. 2 and 44). In order to rotate the shaft 44 by hand, the extremity thereof adjacent the gear 371, 100 is provided with an angular portion 376 (see particularly Figs. 9 and 44) adapted to be engaged by a socket 377 (Fig. 4) carried by a shaft 378, which latter is mounted in suitable bearings and is adjustable longitudinally into and out of engagement with the 105 end of the shaft 44, and the extremity 379 of the shaft 378 is also provided with an angular portion for the reception of a crank or tool by means of which the shaft may be rotated. 110 The machine may be shifted bodily to change its position laterally by means of shifting mechanism embodying spaced drums 380, 381, (Fig. 44) rotatable about upright shafts 382 (Fig. 9), and are arranged at the rear of the main supporting frame. The axles are supported by one extremity by means of the base of the main supporting frame, and are supported at 115 their extremities by means of suitable brackets 383, as shown more clearly in Fig. 44. As the construction and mounting of both of the drums is the same, the description of one will apply to both. The drum is keyed to a sleeve 384 which latter is rotatable upon a bushing 385 surrounding the axle 382, and the sleeve 384 has connected with it a band wheel 386. This band wheel 386 is spaced from the drum 380, and a worm gear 387 is disposed between the drum and 120 125 130

the band wheel 386 and is loosely mounted to rotate upon the sleeve 384. A clutch member 388 is slidably mounted upon the sleeve 384 and is provided with projections 5 389 which pass through suitable openings in the band wheel 386 and are adapted to project into openings 390 in the worm gear 387, so that the worm gear together with the band brake wheel 386 and the drum 10 380, may be locked or unlocked with respect to the worm gear 387 to be rotated by the worm gear when locked and to permit the worm gear to rotate independently with respect thereto when unlocked. The worm 15 gears 387 on the two drums 380, 381 are spaced from each other, as shown in Fig. 44, and arranged between these worm gears is a worm 391 secured to a shaft 392 for rotation therewith, and which shaft is rotatably supported in bearings 393 (Fig. 4). A ball bearing 394 may be provided between the end of the worm 391 and one of the bearings to take up the end thrust. When the shaft 392 is rotated, the worm gears 20 25 387 (Fig. 44) will be rotated, and the drum which is locked for rotation with the respective gears 387 will be rotated while the other drum will remain idle. This is accomplished by shifting the respective clutch members 30 388. Inasmuch as these worm gears 387 are arranged on opposite sides of the shaft 392, they will be rotated in opposite directions. Flexible members 395 (see particularly Fig. 53) are provided which are adapted to be 35 wound around the respective drums at one end, and the free ends of these flexible members are connected as at 396 to arms 397 which are pivotally connected to the main supporting frame as at 398. These flexible 40 members pass over pulleys 399 which are rotatably mounted upon anchor posts or supports 400 which are arranged some distance from the main frame. The pivotal connection of the arms 397 with the main 45 frame, permit the arms to readily move when the drums are rotated, and the winding up of the flexible member or cable on one drum, will shift the machine in that direction and will cause the cable to unwind 50 from the other drum. Obviously, the direction of the shifting movement of the machine may be readily controlled by the clutches 388.

Motion is imparted to the shaft 392 from 55 the shaft 44 (see particularly Fig. 4) through the medium of a gear 401 which is connected with the shaft 44 for rotation, and which gear 401 meshes with the gear 402 journaled in a suitable bearing 403 on the sliding 60 conveyer frame 14. This gear 402 is preferably in the form of a hollow clutch member having a step bearing 404. A clutch member 405 is connected with the shaft 392 and is adapted to project into the clutch gear 65 402 when the sliding structure 14 reaches

the limit of its rearward movement. When these clutch elements are connected together so that they will frictionally bind, the rotation of the shaft 44, will, through the medium of the gears 401 and clutch gears 402, 70 rotate the shaft 392 and the worm 391 and consequently the worm gears 387. In order to force the clutch member 405 into the clutch gear 402, there is provided at the rear end of the machine, a shaft 406 (see also Fig. 43) upon which is mounted an arm 407 (see also Fig. 63), which engages the extremity of the shaft 392. Operating levers 408, one on each side of the machine, are connected with the shaft 406 so as to rock 80 the latter in its bearings 409 (see Fig. 9). Thus by shifting either one of the levers 408, the extremity of the arm 407 engaging the end of the shaft 392, will shift the shaft longitudinally and will force the clutch member 405 into frictional engagement with the other clutch element, and thereby lock the clutch gear 402 for rotation with the shaft 392, through the medium of the gear 401 on the shaft 44 (Fig. 4). 90

As has already been stated, the drums 380, 381, are connected with band brake wheels 386, and are adapted to be locked and unlocked with respect to the worm gears 387. In order to hold the drums 380, 381 against rotation and thereby lock the machine in its adjusted position, band brakes 410 (see particularly Figs. 9, 44 and 45) are provided which encircle the band wheels 386. One extremity of each of the band brakes is pivotally connected to a fixed support 411 (Fig. 9), and the other extremity is connected to an adjustable fastening device 412 which latter is connected with a stationary portion 413 of the frame, and these fastening devices 412 are adapted to be adjusted so as to create sufficient tension on the brakes to cause them to frictionally bind upon the band wheels 386. In order to accomplish this, the fastening device 412 in 100 the present exemplification of the invention, embodies a bolt or threaded shank which passes through the fixed support 413 (Fig. 4), and a nut or collar 414 (Fig. 43) is threaded upon the extremity of the bolt or shank 412 and is adapted to be adjusted thereon by any suitable tool (not shown). When it is desired to adjust the machine or shift it laterally these band brakes 410 are loosened, and after the machine is adjusted laterally either one or both of the brakes 110 may be again tightened.

The clutches 388 (Fig. 44) are adapted to be shifted simultaneously so that when one of the clutch members is shifted to lock the 125 respective drums for rotation, the other is shifted to unlock its drum, and in order to accomplish this, there is provided a shaft 415 (see particularly Figs. 9, 45, 48, 46, 47), which shaft is journaled in suitable bearings 130

416 (see also Fig. 43) extending across the rear of the machine. Connected to this shaft are operating handles or levers 417, 418, arranged adjacent the respective clutch member 388. The lever 417 which is connected to the shaft on one side of the machine, controls the clutch member 388 of the drum 380, and is provided with a portion 419 (see particularly Fig. 46) extending beyond the pivot of the lever, and which portion carries a laterally projecting pin or lug 420. The pin or lug enters the bifurcated extremity 421 of a lever 422, which latter is pivotally connected intermediate its ends as at 423 to a suitable fixed support 424. The free extremity of this lever 422 is preferably in the form of a yoke 425 having lateral projections which enter the usual groove 426 in the clutch member. The lever 418 on the opposite side of the machine which is also connected with the shaft 415, is provided with a laterally projecting pin or lug 427 (see also Fig. 48) which lug is arranged on the side of the pivot of the lever opposite to the side of the pivot on which the lug or projection 420 of the lever 417 is arranged, and this lug or projection 427 enters the bifurcated extremity 428 of a lever 429 which latter is pivoted intermediate its ends as at 430 to a fixed support 431. The other extremity of the lever 429 is preferably in the form of a yoke 432 having lateral extensions projecting into the usual groove 433 in the clutch member.

35 With this construction, and by the arrangement of the lugs or projections 420, 427 on opposite sides of the pivot of the levers, when both levers are in the position shown in Figs. 45, 46, one of the clutches 388

40 will be shifted to unlock its respective worm gear 387 with respect to its drum, and to lock the other worm gear 387 with respect to its drum. When the levers are in an intermediate position, or partially raised,

45 both of the clutch members 388 will be in positions to unlock the worm gears 387 with relation to the drums, and the drums will be free to rotate. When the levers are in a full raised position, the clutch member 388

50 which has assumed an operative or locking position when the levers are lowered to their full extent, will be shifted to unlock its respective drum, and the clutch member on the opposite side of the machine, or the one

55 which assumes an inoperative position when the levers are depressed, will be shifted to lock its respective drum with the worm gear. By the provision of the two levers, it will be manifest that these clutches may be controlled at will and from either side of the machine.

Should it be necessary or desirable to raise or jack up the rear end of the machine, this may be accomplished by means of an ordinary jack which may be placed beneath the

rearwardly projecting portions or brackets 434 arranged at the rear of the machine, and which are connected with any fixed portion of the main frame such as the support 413 (see particularly Figs. 2, 4, 43 and 45). 70

It is thought that the operation of this improved machine will be fully understood from the above description, but briefly stated it is as follows, reference being had particularly to Figs. 1 to 4. 75

When the machine is first positioned in the mine, and assuming the parts to be in the position shown in the figures referred to, the motor is started which will operate the motor-shaft. All of the mechanism will then 80 be operated, and after the clutch 71 (Fig. 93) by means of the lever 78 (Figs. 1 and 9) has been set to lock the advancing gear 65 to the shaft 51, to feed the sliding superstructure forwardly upon the main frame, 85 (Figs. 2 and 52) the cutter 31, 32 which makes the horizontal kerf or cut adjacent the floor of the room, operates upon the material to be mined to make such cut. At the same time the cutters 150 will be operated 90 but are located with their cutting planes or edges slightly in the rear of the forward cutting planes of the cutter 31, 32. As this horizontal kerf or cut is being made, the sliding structure which supports the cutter 150 as well as the cutter 31, 32, will be slowly advanced by the racks 11 and the pinions 49 (Fig. 2). When the cutters 150 contact with the material, they will make the

upright or vertical cuts or kerfs and will 100 advance some distance into the wall of the material by the forward movement of the sliding structure. During this operation, the breaking down tools will be operated through the medium of the cranks 245 and 105

the oscillating members 236 (see also Fig. 31), which latter will reciprocate the sliding cross-head 226 to move it into a position that the dogs 228 will catch the stems 220 of the breaking down tools and will withdraw them 110

so that the elastic members 225 of the breaking down tools will be placed under compression, and when the cross-head 226 is moved in the opposite direction, the dogs 228 will be tripped to release the tools which 115

latter will then be forcibly projected so that the picks 211 will strike the wall of the material to be mined and break the material down (Fig. 38). The material thus dislodged will fall upon the platform 92 (Fig. 120

3) of the endless conveyer 90 and between the cutters 150. The dislodged material will then be caught by the conveyer 90 (Fig. 10) and conveyed thereby to the discharge end of the conveyer (Fig. 2) from which it 125 will be discharged into the hopper 334 (Figs. 2 and 4) of the supplemental conveyer to be conveyed by the latter to any suitable point or to be loaded. The supplemental conveyer being rotatably or swingingly mount- 130

ed upon the sliding structure, will travel forwardly with the sliding structure so that the hopper will always be maintained under the discharge end of the main conveyer and 5 can also be swung upon its pivot so that its discharge end may be positioned as is desired.

When sufficient compression has been created upon the elastic members 225, (Fig. 38) 10 resistance will be exerted on the gears 253, 252, (see also Fig. 31) to a sufficient degree to overcome the resistance between the gears 111, 252, and this will lock the gear 252 with respect to the gear 111 so that the rotation 15 of the latter will cause the gear 252 to "walk" around the gear 111, which operation will rock the segments 284 of the breaking down means in a direction to elevate the forward end of the breaking down means, 20 and thereby feed the breaking down means upwardly automatically. In order that this feeding movement of the breaking down means shall be automatic, the mechanism shown in Fig. 54 is provided, and as the gear 25 300 which meshes with the gear 111 is rotated, the tappet 299 carried by the gear 300, will rock the lever 294 and retract the dog 287 to permit the gear 111, when the gear 252 is locked, to move the segment 284 35 one step, after which the tappet 299 will pass out of engagement with the lever 294 to permit the dog 287 to return or move into the next notch of the segment and lock the latter against further feeding movement.

35 This operation will continue as long as desired or until the sliding structure has reached the limit of its advancing movement upon the stationary frame. The sliding structure is then returned or moved back- 40 wardly upon the main supporting frame with a quick return movement, and is accomplished by again shifting the clutch member 71 so as to lock the gear 57 with the shaft 51 and release the gear 65 (Figs. 30 and 93), 45 the gear 57 being of a higher speed than the gear 65. After the sliding structure has reached the limit of its return movement, the clutch member 71 is again shifted to unlock the gear 57 and lock the gear 65 when the 50 operation will be repeated. In order that the clutch member 71 may be automatically shifted when the sliding structure reaches the limit of its movements in the respective directions, the stops 80, 81 (Figs. 1 and 2) 55 are provided on the main or stationary supporting structure with which an arm or lever 79 on the shaft 76 which controls the clutch member 71, coöperates.

During the feeding movement of the sliding structure, the cutters 150 are oscillated about their points of pivotal support through the medium of the gear 179 (Figs. 1 and 2) and the adjustable connection 191, 194 (Fig. 24) between the supporting arms 152 of the 60 cutters and the gear, so that the cutters 150

will command the entire vertical area of the material being operated upon. Should it be desired to vary the degree of oscillating movement of the cutters 150, the connection 191, 194 between the gears 179 and the supporting arms 172 is adjusted, and by the provision of the specific adjusting means herein described, the cutters 150, although their degree of oscillating movement may be varied, will always return to the same point, 75 that is, the limit of the downward movement of the cutters will always be fixed while the limit of the upward movement may be varied. This is advisable because if the cutters 150 should be lowered below a fixed 80 point, they would contact with other portions of the mechanism, especially the portions of the mechanism which project under the cutters 150 which would result in considerable damage.

The breaking down tool may be readily adjusted to any desirable position by throwing the feeding mechanism as shown in Fig. 54, out of operation, at which time the breaking down mechanism will be free to oscillate 85 in either direction about its point of pivotal support, and the weight of this mechanism in front of the pivot is slightly greater than the tension of the elastic members 276, which latter operates to assist in counterbalancing 90 the structure. When the breaking down means is thus released, the forward end or the picks 211 thereof will drop to their lowermost position or in close proximity to the platform 92, and their descent may be 95 retarded or controlled by the band brakes 327. When in this position, the breaking down means will commence to operate upon the wall of the material to be mined in close proximity to the horizontal cut or kerf, and this breaking down means is so arranged with respect to the cutters 150 as to operate 100 between them and between the vertical cuts or kerfs made thereby. When the breaking down means is thus positioned in its lowermost position, the feeding mechanism may be thrown into operation and thereby cause the breaking down means to be automatically 105 and intermittently raised or fed into another position to take a new hold or strike upon 110 the material being mined.

Should it be desired to render one of the cutters 150 or even both of them inoperative so that they will not be actuated during the actuation of the remaining portion of 115 the machine, this may be accomplished by shifting either one or both of the clutches 188 (see Fig. 7) by operating the levers 190.

The feeding of the breaking down means 120 upwardly may be prevented by shifting the rod 313 (see also Fig. 32) which will adjust the incline grooved or cam member 317 so as to move the stops 232 into positions 125 that the extremities 233 of the dogs 228 130

will not engage the stops, and therefore the dogs will not be positioned to catch the stems 220 of the breaking down tools which will permit the cross-head 226 to reciprocate freely without retracting the breaking down tools. This, therefore, will prevent the tension from being created upon the elastic members 225, and without this tension the necessary resistance will not be imparted to the gears 253 to lock the gears 252, and therefore the segments 284 will not be elevated or rocked by the gears 111 with the result that the breaking down means will not be automatically fed.

15 With machines of this class, the coal or material being mined will break away for some considerable distance in advance of the picks 211, when the latter strike the material, and will thereby afford sufficient space for the breaking down tools to drop or be moved to their lowered positions.

Some coal, however, will not break away in advance of the picks when the latter strike the material, and therefore the picks 25 cannot readily be lowered inasmuch as they would engage the wall of the material if it did not break away sufficiently to permit the picks to be lowered. Therefore, in order to provide means whereby the picks 30 may be held in their retracted positions, so that they can be readily lowered, the catches 318, 319 (Fig. 38) are provided which may be adjusted by the rod 313 into positions that they will engage the shouldered portions 322 on the sockets 210 of the picks, and thereby lock the latter in their retracted positions so that they will clear the wall of the material sufficiently to permit them to be readily lowered. After the 40 picks or breaking down means have been thus lowered, the rod 313 may be shifted in the opposite direction to release the picks so that the elastic members 225 will project them and hold them in proper positions so that they may be operated. The catches 318, 319 are so connected with the rod 313, that the latter may be adjusted to shift the stops 232 without affecting the catches.

50 What is claimed as new is:

1. In a mining machine, a framework, vertically arranged cutters mounted on opposite sides of said framework at the front end thereof, a horizontally arranged cutter mounted on said framework at the front end thereof, said cutters being arranged to operate in advance of said framework in combination with a platform carried by the front end of said framework and arranged 55 to receive material dislodged within the boundary of said cutters, means for operating said cutters, and a continuously operated conveyer extending into the kerf produced by said horizontally arranged cutter, and removing the material as fast as dis-

lodged, in a direction parallel to the planes of said side cutters.

2. In a mining machine, the combination with breaking down mechanism mounted for up and down movement, of automatic means for giving said breaking down mechanism successive short feeding movements all in an upward direction, apparatus permitting movement of said breaking down mechanism in the downward direction by gravity, and means for holding the breaking down mechanism from movement up or down while occupying a position between said successive feeding movements.

3. In a mining machine, the combination with breaking down means mounted for pivotal movement upwardly and downwardly, of mechanism for feeding the breaking down means in steps in the upward direction during successive intervals, and brake-mechanism under the control of the operator for holding said breaking down means in any of its positions during operation.

4. In a mining machine, the combination with breaking down mechanism movable in one direction by gravity, of means for feeding said breaking down mechanism in the other direction in short steps and alternately stopping the same, apparatus for effecting the operation of said breaking down means during the stopping intervals, a brake for retarding the movement of said breaking down mechanism by gravity, and means operated upon the application of said brake for releasing said stopping means.

5. In a mining machine, the combination with breaking down mechanism mounted for pivotal movement upwardly and downwardly, automatic means for moving the breaking down mechanism above the pivot in short successive steps all in the upward direction comprising a device for automatically holding the breaking down mechanism stationary at regularly recurring intervals between such steps of movement, and apparatus for rendering said automatic feeding means inactive for permitting the breaking down mechanism to move about its pivot in the opposite direction by gravity.

6. In a machine of the class described, the combination of breaking down means mounted for pivotal movement upwardly and downwardly, means for automatically and intermittently moving the said breaking down means about its pivot in one direction, and means for rendering the last said means inactive for permitting the breaking down means to move about the pivot in the opposite direction and by gravity.

7. In a mining machine, the combination with cutting mechanism, of means for feed-

ing said cutting mechanism step by step in short successive movements with intermediate intervals of stopping, and latch mechanism for holding said cutting mechanism 5 against movement in any direction during such stopping intervals.

8. In a mining machine, the combination with a frame, of breaking down mechanism pivoted thereto, apparatus for intermittently moving said breaking down mechanism on its pivot in one direction in short successive steps with intervening intervals of stopping, apparatus for holding said breaking down mechanism against movement in either direction during such stopping intervals, and means under the control of the operator for releasing said holding apparatus and permitting said breaking down mechanism to move back toward initial position.

9. In a mining machine, the combination with means for undercutting a body of coal, of receiving means adapted to project into the kerf made by said cutting means, and a conveyer having superposed portions travelling in opposite directions and extending into said kerf within said receiving means and having its upper portion thereof always operating approximately in the plane of said receiving means to carry broken down coal 30 directly back from the mine wall.

10. In a machine of the class described, the combination of breaking down means, operating mechanism therefor embodying mechanism for automatically feeding the 35 breaking down means to the work, and means for rendering inactive that portion of the mechanism which effects the feeding movement while the operating mechanism remains active, and embodying means under 40 the control of the operator for holding the said breaking down means in any of its adjusted positions when the feeding mechanism is rendered inactive, said breaking down means being freely movable in the 45 opposite direction when the feeding mechanism and the said holding means are rendered inactive.

11. In a machine of the class described, the combination of breaking down means, 50 operating mechanism therefor embodying mechanism for automatically feeding the breaking down means step by step in the same direction to alternate with stopping periods of operation of said breaking-down means, and means under the control of the operator for rendering inactive that portion of the mechanism which effects the feeding movement while the operating mechanism remains active and embodying a brake 55 mechanism under the control of the operator for holding the breaking down means in any of its adjusted positions when the feeding mechanism is rendered inactive to cause the breaking-down means to act repeatedly 60 in such adjusted positions.

12. In a machine of the class described, the combination of breaking down means, operating mechanism therefor embodying mechanism for intermittently feeding the breaking down means to the work, and 70 means under the control of the operator for rendering inactive that portion of the mechanism which effects the feeding movement while the operating mechanism remains active and embodying a brake mechanism under the control of the operator for holding the breaking down means in any of its adjusted positions when the feeding mechanism is rendered inactive.

13. In a machine of the class described, 80 the combination of breaking down means embodying a tool mounted for pivotal movement, operating mechanism for the tool embodying means for automatically and intermittently moving the tool about its pivot in one direction, and means for rendering inactive that portion of the mechanism which moves the tool about its pivot, whereby the said tool may swing freely about its pivot in either direction.

14. In a machine of the class described, the combination of breaking down means embodying a tool mounted for pivotal movement, operating mechanism for the tool embodying means for intermittently and automatically moving the tool about its pivot in one direction, and means for rendering inactive the last recited means, whereby the tool may be moved about its pivot automatically in the opposite direction and automatically from any position into which it has been moved by the second recited means.

15. In a machine of the class described, the combination of breaking down means embodying a tool mounted for pivotal movement, operating mechanism for the tool embodying means for intermittently and automatically moving the tool about its pivot in a vertical direction, and means for rendering inactive at will the last recited means, whereby the tool may be moved automatically about its pivot in the opposite direction when released and from any position into which it has been moved by the second recited means.

16. In a machine of the class described, the combination of a pivotally mounted cutter support, a cutter reciprocably mounted in the support, resilient means tending to force the cutter forwardly into the material to be mined, and means for retracting said cutter, said retracting means operating to create a stress upon the said resilient means whereby the cutter support will be moved about its pivot.

17. In a machine of the class described, the combination of a pivotally mounted cutter support, a cutter reciprocably mounted in the support, resilient means tending to force the cutter forwardly into the mate- 130

rial to be mined, means for retracting said cutter, said retracting means operating to create a stress upon the said resilient means whereby the cutter support will be moved about its pivot, and means for releasing the said retracting means at the limit of the retracting movement.

18. In a machine of the class described, the combination of a pivotally mounted cutter support, a cutter reciprocably mounted in the support, resilient means tending to force the cutter forwardly into the material to be mined, means for retracting said cutter, said retracting means operating to create a stress upon the said resilient means whereby the cutter support will be moved about its pivot, and means for holding the cutter support in any of its adjusted positions and against movement under the influence of the said retracting means.

19. In a machine of the class described, the combination of a pivotally mounted cutter support, a cutter reciprocably mounted on the support, resilient means tending to force the cutter forwardly into the material to be mined, retracting means, means for operating the latter to retract the cutter upon each operation of the retracting means to create a stress upon the said resilient means whereby the cutter support will be moved about its pivot, and means for causing the said retracting means to operate one or more times without retracting the cutter.

20. In a machine of the class described, the combination of a pivotally mounted cutter support, a cutter reciprocably mounted on the support, resilient means tending to force the cutter forwardly into the material to be mined, retracting means, means for operating the latter to retract the cutter upon each operation of the retracting means to create a stress upon the said resilient means whereby the cutter support will be intermittently moved about its pivot, and means for causing the said retracting means to operate one or more times without retracting the cutter.

21. In a machine of the class described, the combination of a pivotally mounted cutter support, a cutter reciprocably mounted on the support, means for forcing the cutter forwardly into the material to be mined, retracting means, means for operating the latter to retract the cutter upon each operation of the retracting means to create a stress upon the first recited means and for moving the cutter support about its pivot upon each retraction of the cutter, and means for causing the retracting means to retract the cutter one or more times at will without moving the cutter support about its pivot.

22. In a machine of the class described, the combination of a pivotally mounted cutter support, a cutter reciprocably mounted on the support, means for forcing the cut-

ter forwardly into the material to be mined, retracting means, means for operating the latter to retract the cutter upon each operation of the retracting means to create a stress upon the first recited means and for 70 moving the cutter support about its pivot upon each retraction of the cutter, and means under the control of the operator for causing the retracting means to retract the cutter one or more times at will without 75 moving the cutter support about its pivot.

23. In a machine of the class described, the combination of a pivotally mounted cutter support, a cutter reciprocably mounted thereon, means for forcing the cutter forwardly and into the material to be mined, retracting means, means for operating the latter to retract the cutter to create a stress upon the first recited means to cause the said operating mechanism to also move the 80 cutter support about its pivot, and means for holding the cutter support against the last recited movement and in any position to which the cutter support has been moved.

24. In a machine of the class described, the combination of a pivotally mounted cutter support, a cutter reciprocably mounted thereon, means for forcing the cutter forwardly and into the material to be mined, retracting means, means for operating the 90 latter to retract the cutter to create a stress upon the first recited means to cause the said operating mechanism to also move the cutter support about its pivot, means for holding the cutter support against the last 95 recited movement and in any position to which the cutter support has been moved, and means whereby the cutter support may be freely moved about its pivot in either direction.

25. In a machine of the class described, the combination of a pivotally mounted cutter support, a cutter reciprocably mounted thereon, means for forcing the cutter forwardly and into the material to be mined, retracting means, means for operating the latter to retract the cutter to create a stress upon the first recited means to cause the said operating mechanism to also move the cutter support about its pivot, and brake 110 mechanism under the control of the operator and co-operating with the cutter support for maintaining the support in any of the adjusted positions to which it has been moved.

26. In a machine of the class described, the combination of a pivotally mounted cutter support, a cutter reciprocably mounted thereon, means for forcing the cutter forwardly and into the material to be mined, retracting means, means for operating the latter to retract the cutter to create a stress upon the first recited means to cause the said operating mechanism to also move and advance the cutter support about its pivot, and means for respectively locking and un- 130

locking the cutter support upon each movement of the said retracting means, whereby the movement of the cutter frame will be intermittent.

- 5 27. In a machine of the class described, the combination of a pivotally mounted cutter support, a cutter reciprocably mounted thereon, means for forcing the cutter forwardly and into the material to be mined, 70
 10 retracting means, means for operating the latter to retract the cutter to create a stress upon the first recited means to cause the said operating mechanism to also move and advance the cutter support about its pivot, 75
 15 and means operatively related to the said operating mechanism for respectively locking and unlocking the cutter support upon each movement of the said retracting means, whereby the movement of the cutter frame 80
 20 will be intermittent.
28. In a machine of the class described, the combination of a pivotally mounted cutter support, a cutter reciprocably mounted thereon, means for forcing the cutter forwardly and into the material to be mined, 85
 25 retracting means, means for operating the latter to retract the cutter to create a stress upon the first recited means to cause the said operating mechanism to also move and
 30 advance the cutter support about its pivot, means for respectively locking and unlocking the cutter support upon each movement of the said retracting means, whereby the movement of the cutter frame will be intermittent, and means for rendering the said locking means inactive. 90
 35
29. In a machine of the class described, the combination of a pivotally mounted cutter support, a cutter reciprocably mounted thereon, means for forcing the cutter forwardly and into the material to be mined, 95
 40 retracting means, means for operating the latter to retract the cutter to create a stress upon the first recited means to cause the said operating mechanism to also move and advance the cutter support about its pivot, means for respectively locking and unlocking the cutter support upon each movement of the said retracting means, whereby the movement of the cutter frame will be intermittent, and means for holding the cutter support against pivotal movement by the said operating mechanism. 100
 45
30. In a machine of the class described, the combination of a pivotally mounted cutter support, a cutter reciprocably mounted thereon and also movable upwardly and downwardly about the pivot of the frame, means for sustaining a portion of the weight 110
 50 of said cutter and frame, means for reciprocating the cutter, the last said means embodying means operating to move the cutter upwardly, and means for maintaining the cutter in its adjusted position. 115
 55
- 60 31. In a machine of the class described, 120
 65

the combination of a pivotally mounted cutter support, a cutter reciprocably mounted thereon and also movable upwardly and downwardly about the pivot of the frame, 70
 75 resilient means for sustaining a portion of the weight of said cutter and frame, means for reciprocating the cutter, the last said means embodying means operating to move the cutter upwardly, and means for maintaining the cutter in its adjusted position. 75

32. In a machine of the class described, the combination of a pivotally mounted cutter support, a cutter reciprocably mounted thereon, means for sustaining a portion of the weight of the frame and cutter, 80
 85 means for reciprocating the cutter on the support and embodying means for retracting the cutter, means for forcing the cutter forwardly and into the work, the second recited means operating as the cutter is retracted to move the cutter support about its pivot, and means for releasing the said retracting movement. 85

33. In a machine of the class described, 90
 95 the combination of a pivotally mounted cutter support, a cutter reciprocably mounted thereon, means for sustaining a portion of the weight of the frame and cutter, means for reciprocating the cutter on the support and embodying means for retracting the cutter, means for forcing the cutter forwardly and into the work, the second recited means operating as the cutter is retracted to move the cutter support about its pivot, means for releasing the said retracting movement at the limit of its retracting movement, and means for holding the cutter frame against pivotal movement when the said retracting means is released. 100
 105

34. In a machine of the class described, the combination of a pivotally mounted cutter support, a cutter reciprocably mounted thereon, means for sustaining a portion of the weight of the frame and cutter, 110
 115 means for reciprocating the cutter on the support and embodying means for retracting the cutter, means for forcing the cutter forwardly and into the work, the second recited means operating as the cutter is retracted to move the cutter support about its pivot, means for holding the cutter support against such pivotal movement during the operating of the said retracting means, and means for releasing the retracting means 120
 at the limit of its retracting movement. 125

35. In a machine of the class described, the combination of a pivotally mounted pick support, a pick reciprocably mounted thereon, a spring for forcing the cutter forwardly and into engagement with the work, means for retracting the said pick against the action of said spring, means for feeding the pick support in one direction about its pivot, means for holding the pick retracted 130

against the stress of the said spring, and means for rendering the said feeding means inactive whereby said pick support may be moved about its pivot in the opposite direction by gravity.

36. In a machine of the class described, the combination of a pivotally mounted cutter support, a cutter reciprocably mounted thereon, resilient means for sustaining a portion of the weight of the frame, means for forcing the cutter forwardly and into engagement with the work, means for retracting the cutter, means for feeding the cutter support in one direction, about its pivot, means for holding the cutter retracted against the stress of the first recited means, and means for rendering the said feeding means inactive whereby the cutter support may be moved freely about its pivot in the opposite direction, the first recited means serving as a cushion for the cutter frame during the last said movement thereof.

37. In a machine of the class described, the combination of a main support, a cutter support pivotally connected adjacent one extremity with the main support, a cutter reciprocably mounted upon its cutter support, resilient means adjacent the pivot of the cutter support for sustaining a portion of the weight of the cutter frame, means for forcing the cutter forwardly into engagement with the work, retracting means for the cutter, means for operating the retracting means, said retracting means also operating to feed the cutter support about its pivot, upon each operation thereof, and means for restraining the cutter against pivotal movement under the influence of the said retracting means.

38. In a machine of the class described, the combination of a main support, a cutter support pivotally connected adjacent one extremity with the main support, a cutter reciprocably mounted upon the cutter support, resilient means adjacent the pivot of the cutter support for sustaining a portion of the weight of the cutter frame, means for forcing the cutter forwardly into engagement with the work, retracting means for the cutter, means for operating the retracting means, said retracting means also operating to feed the cutter support about its pivot upon each operation thereof, and means for rendering the retracting means inoperative with respect to the cutter support whereby the latter may be freely moved about its pivot in the opposite direction.

39. In a machine of the class described, the combination of a main support, a cutter support pivotally connected adjacent one extremity with the main support, a cutter reciprocably mounted upon the cutter support, resilient means adjacent the pivot of the cutter support for sustaining a portion of the weight of the cutter frame, means for

forcing the cutter forwardly into engagement with the work, retracting means for the cutter, means for operating the retracting means, said retracting means also operating to feed the cutter support about its pivot upon each operation thereof, and means for rendering the retracting means inoperative with respect to the cutter support whereby the latter may be freely moved about its pivot in the opposite direction and by gravity.

40. In a machine of the class described, the combination of a main support, a cutter support pivotally connected adjacent one extremity with the main support, a cutter reciprocably mounted upon its cutter support, resilient means adjacent the pivot of the cutter support for sustaining a portion of the weight of the cutter frame, means for forcing the cutter forwardly into engagement with the work, retracting means for the cutter, means for operating the retracting means, said retracting means also operating to feed the cutter support about its pivot upon each operation thereof, means for restraining the cutter support against such movement, and means for rendering the said retracting means inactive with respect to the cutter, whereby the cutter support may be freely moved about its pivot in the opposite direction.

41. In a machine of the class described, the combination of a main support, a cutter support pivotally connected adjacent one extremity with the main support, a cutter reciprocably mounted upon the cutter support, means for forcing the cutter forwardly and into engagement with the work, retracting means for the cutter, and embodying means for feeding the cutter support in one direction about its pivot, and means for locking the cutter in a retracted position during the movement of the cutter support about its pivot in the opposite direction.

42. In a machine of the class described, the combination of a main support, a cutter support pivotally connected adjacent one extremity with the main support, a cutter reciprocably mounted upon the cutter support, means for forcing the cutter forwardly and into engagement with the work, retracting means for the cutter and embodying means for feeding the cutter support in one direction about its pivot, means for locking the cutter in a retracted position, and means for rendering the retracting means inactive with respect to the cutter whereby the cutter support may be moved freely about its pivot in the opposite direction.

43. In a machine of the class described, the combination of a main support, a cutter support pivotally connected adjacent one extremity with the main support, a cutter reciprocably mounted upon the cutter support, means for forcing the cutter forwardly

and into engagement with the work, retracting means for the cutter and embodying means for feeding the cutter support in one direction about its pivot, means for locking the cutter in a retracted position, and means operatively related to the last said means for rendering the retracting means inactive with respect to the cutter whereby the cutter support may be moved freely about its pivot

5 10 in the opposite direction.

44. In a machine of the class described, the combination of a main support, a cutter support pivotally connected adjacent one extremity with the main support, a cutter reciprocably mounted upon the cutter support, means for forcing the cutter forwardly and into engagement with the work, retracting means for the cutter and embodying means for feeding the cutter support

15 20 in one direction about its pivot, means for locking the cutter in a retracted position, means for rendering the retracting means inactive with respect to the cutter, and means common to the last said means and the said locking means for actuating them, and embodying means whereby one may be operated independently with respect to the other.

45. In a machine of the class described, the combination of a main support, a cutter support pivotally connected adjacent one extremity with the main support, a cutter reciprocably mounted upon the cutter support, means for forcing the cutter forwardly and into engagement with the work, retracting means for the cutter and embodying means for feeding the cutter support in one direction about its pivot, means for locking the cutter in a retracted position, means for rendering the retracting means inactive with respect to the cutter, and means common to the last said means and the said locking means for actuating them, and embodying means whereby either one

30 35 40 45 may be actuated without actuating the other and at will.

46. In a machine of the class described, the combination of a pivotally mounted support, a cutter reciprocable thereon, means for actuating the cutter embodying a series of gears, and means for operating the gears to actuate the cutter, said actuating means also embodying means for causing the same gears to shift the cutter support about its pivot.

47. In a machine of the class described, the combination of a pivotally mounted support, a cutter reciprocable thereon, means for actuating the cutter embodying a series of gears, means for operating the gears to actuate the cutter, said actuating means also embodying means for causing the same gears to shift the cutter support about its pivot, and means for maintaining the cutter sup-

port in any position to which it has been moved.

48. In a machine of the class described, the combination of a pivotally mounted support, a cutter reciprocable thereon, means for actuating the cutter embodying a series of gears, means for operating the gears to actuate the cutter, said actuating means also embodying means for causing the same gears to shift the cutter support about its pivot, and means under the control of the operator for maintaining the cutter support in any position to which it has been moved and against such shifting movement.

49. In a machine of the class described, the combination of a pivotally mounted support, a cutter movably mounted thereon, means for actuating the cutter embodying gears carried by the support, and a gear mounted upon another support, and means for operating the gears to retract the cutter, said cutter retracting means also embodying means for causing said gears to move the cutter support about its pivot, after retraction of said cutter a predetermined distance.

50. In a machine of the class described, the combination of a pivotally mounted support, a cutter movably mounted thereon, means for operating the cutter embodying gears mounted upon the cutter support and a gear mounted upon a fixed support, the first said gears being capable of bodily movement with respect to the second said gear and all of said gears being capable of rotary motion with respect to each other, and means for imparting such rotary motion to the gears to actuate the cutter, the said cutter operating means also embodying means for causing the said bodily movement of the gears to shift the cutter support about its pivot.

51. In a machine of the class described, the combination of a pivotally mounted support, a cutter movably mounted thereon, means for operating the cutter embodying gears mounted upon the cutter support and a gear mounted upon a fixed support, the first said gears being capable of bodily movement with respect to the second said gear and all of said gears being capable of rotary motion with respect to each other, means for imparting such rotary motion to the gears to actuate the cutter, the said cutter operating means also embodying means for causing the said bodily movement of the gears to shift the cutter support about its pivot, and means for retaining the cutter support in any position to which it has been moved.

52. In a machine of the class described, the combination of a pivotally mounted support, a cutter movably mounted thereon, means for operating the cutter embodying gears mounted upon the cutter support and

- a gear mounted upon a fixed support, the first said gears being capable of bodily movement with respect to the second said gear and all of said gears being capable of 5 rotary motion with respect to each other, and means for imparting such rotary motion to the gears to actuate the cutter, the said cutter operating means also embodying means for causing the said bodily movement 10 of the gears to shift the cutter support about its pivot, and means for holding the gears against said bodily movement while the cutter operating mechanism remains active.
- 15 53. In a machine of the class described, the combination of a pivotally mounted cutter support, a cutter movably mounted thereon, means for actuating the cutter upon its support and embodying intermeshing 20 gears capable of different movements with respect to each other, and means for imparting one of such movements to the gears for actuating the cutter, said actuating means also embodying means for imparting another and different movement to the gears with respect to each other for shifting the cutter support about its pivot.
54. In a machine of the class described, the combination of a pivotally mounted cutter support, a cutter movably mounted thereon, means for actuating the cutter upon its support and embodying intermeshing 30 gears capable of different movements with respect to each other, and means for imparting one of such movements to the gears for actuating the cutter, said actuating means also embodying means for imparting another and different movement to be imparted to the gears for shifting the cutter support.
- 35 55. In a machine of the class described, the combination of a pivotally mounted cutter support, a cutter movably mounted thereon, means for actuating the cutter upon its support and embodying intermeshing 40 gears capable of different movements with respect to each other, and means for imparting one of such movements to the gears for actuating the cutter, said actuating means also embodying means for imparting another and different movement to the gears with respect to each other for intermittently shifting the cutter support about its pivot.
- 45 56. In a machine of the class described, the combination of a pivotally mounted cutter support, a cutter movably mounted thereon, means for actuating the cutter upon its support and embodying intermeshing 50 gears capable of different movements with respect to each other, and means for imparting one of such movements to the gears for actuating the cutter, said actuating means also embodying means for imparting another and different movement to the gears with respect to each other for automatically shifting the cutter support about its pivot.
- 55 57. In a machine of the class described, the combination of a movably mounted cutter support, a cutter movably mounted thereon, means for actuating the cutter with respect to the support, and embodying intermeshing gears capable of different movements with respect to each other, and means for imparting one of such movements to the gears to operate the cutter, said cutter actuating means embodying means for causing another and different movement to be imparted to the gears for shifting the cutter support.
- 60 58. In a machine of the class described, the combination of a movably mounted cutter support, a cutter reciprocably mounted upon the support, means for reciprocating the cutter, embodying intermeshing gears capable of different movements with respect to each other, and means for imparting one of such movements to the gears to operate the cutter, said cutter operating means embodying means for causing another and different movement to be imparted to the gears for moving the cutter support.
- 65 59. In a machine of the class described, the combination of a movably mounted cutter support, a cutter reciprocably mounted upon the support, means for projecting the cutter into engagement with the work, retracting means, means for operating the latter for retracting the cutter, embodying a series of intermeshing gears capable of different movements with respect to each other, and means for imparting one of such movements to the gears to operate the retracting means to create stress upon the first recited means, the stress thus created also operating to impart another and different movement to the gears to shift the cutter support.
- 70 60. In a machine of the class described, the combination of a movably mounted cutter support, a cutter reciprocably mounted upon the support, means for projecting the cutter into engagement with the work, retracting means, means for operating the latter for retracting the cutter, embodying a series of intermeshing gears capable of different movements with respect to each other, means for imparting one of such movements to the gears to operate the retracting means to create stress upon the first recited means, the stress thus created also operating to impart another and different movement to the gears to shift the cutter support upon each operation of the said retracting means, and means for causing the said retracting means to operate one or more times without imparting the last recited movement to the gears.

61. In a machine of the class described, the combination of a movably mounted cutter support, a cutter reciprocably mounted upon the support, means for projecting the cutter into engagement with the work, retracting means, means for operating the latter for retracting the cutter, embodying a series of intermeshing gears capable of different movements with respect to each other, means for imparting one of such movements 70 to the gears to operate the retracting means to create stress upon the first recited means, the stress thus created also operating to impart another and different movement to the gears to shift the cutter support, upon each 75 operation of the retracting means, means for rendering the cutter and cutter support capable of free movement in the opposite direction by gravity, and means for holding the cutter retracted during the last said 80 movement thereof.
62. In a machine of the class described, the combination of a movably mounted cutter support, a cutter reciprocably mounted upon the support, means for projecting the cutter into engagement with the work, retracting means, means for operating the latter for retracting the cutter, embodying a series of intermeshing gears capable of different movements with respect to each other, 90 means for imparting one of such movements to the gears to operate the retracting means to create stress upon the first recited means, the stress thus created also operating to impart another and different movement to the gears to shift the cutter support, upon each 95 operation of the retracting means, means for rendering the cutter and cutter support capable of free movement in the opposite direction by gravity, means for holding the cutter retracted during the last said 100 movement thereof, and means for sustaining a portion of the weight of the cutter support.
63. In a machine of the class described, the combination of a movably mounted cutter support, a cutter reciprocably mounted upon the support, means for projecting the cutter into engagement with the work, retracting means, means for operating the latter for retracting the cutter, embodying a series of intermeshing gears capable of different movements with respect to each other, 110 means for imparting one of such movements to the gears to operate the retracting means to create stress upon the first recited means, the stress thus created also operating to impart another and different movement to the gears to shift the cutter support upon each 115 operation of the retracting means, means for rendering the cutter and cutter support capable of free movement in the opposite direction by gravity, means for holding the cutter retracted during the last said movement thereof, and resilient means for sustaining a portion of the weight of the cutter 120 support, and also operating as a cushion for the cutter support during the last said movement thereof.
64. In a machine of the class described, the combination of a movably mounted cutter support, a cutter reciprocably mounted upon the support, means for projecting the cutter into engagement with the work, re- 125
65. In a machine of the class described, the combination of a movably mounted cutter support, a cutter reciprocably mounted upon the support, means for projecting the cutter into engagement with the work, retracting means, means for operating the latter for retracting the cutter, embodying a series of intermeshing gears capable of different movements with respect to each other, 130

zontal cut, means for making a vertical cut, means disposed to operate in the angle between the first two said means for breaking down the material, said breaking down means being adapted for movement upwardly and downwardly, and means for intermittently feeding the breaking down means upwardly.

68. In a machine of the class described, the combination of means for making a horizontal cut, means for making a vertical cut, means disposed to operate in the angle between the first two said means for breaking down the material, said breaking down means being adapted for movement upwardly and downwardly, means for intermittently feeding the breaking down means upwardly, and means for rendering the said feeding means inactive whereby the breaking down means may be freely moved downwardly.

69. In a machine of the class described, the combination of means for making a horizontal cut, means for making a vertical cut, means disposed to operate in the angle between the first two said means for breaking down the material, said breaking down means being adapted for movement upwardly and downwardly, means for intermittently feeding the breaking down means upwardly, and means for rendering the said feeding means inactive whereby the breaking down means may be freely moved downwardly by gravity.

70. In a machine of the class described, the combination of means for making a horizontal cut, means for making a vertical cut, means disposed to operate in the angle between the first two said means for breaking down the material, said breaking down means being adapted for movement upwardly and downwardly, and means for intermittently feeding the breaking down means in a constant direction.

71. In a machine of the class described, the combination of means for making a horizontal cut, means for making a vertical cut, means disposed to operate in the angle between the first two said means for breaking down the material, said breaking down means being adapted for movement upwardly and downwardly, means for intermittently feeding the breaking down means in a constant direction, and means for removing the broken down material back from the mine wall.

72. In a machine of the class described, the combination of means for making a horizontal cut, means for making a vertical cut, means disposed to operate in the angle between the first two said means for breaking down the material, said breaking down means being adapted for movement upwardly and downwardly, means for intermittently feeding the breaking down means

in a constant direction, and a conveyer for receiving the material directly as it is broken down for conveying it away and above which conveyer the said breaking down means operates.

70

73. In a machine of the class described, the combination of a slidable support, means for making a horizontal cut, means for making a vertical cut, means disposed to operate in the angle between the first two said means for breaking down the material, said breaking down means being adapted for movement upwardly and downwardly, means for intermittently feeding the breaking down means in one direction, all of said parts being mounted on the slidable support, and a conveyer on the support and operating below the breaking down means for receiving the broken down material.

75

74. In a machine of the class described, the combination of a slidable support, means for making a horizontal cut, means for making a vertical cut, means disposed to operate in the angle between the first two said means for breaking down the material, said breaking down means being adapted for movement upwardly and downwardly, means for intermittently feeding the breaking down means in one direction, all of said parts being mounted on the slidable support, and a conveyer on the support for operating below the breaking down means for receiving the broken down material.

80

85

75. In a machine of the class described, the combination of a slidable support, means for making a horizontal cut, means for making a vertical cut, means disposed to operate in the angle between the first two said means for breaking down the material, said breaking down means being adapted for movement upwardly and downwardly, means for intermittently feeding the breaking down means in one direction, all of said parts being mounted on the slidable support, a conveyer on the support and operating below the breaking down means for receiving the broken down material, a common source of power for operating the parts and for moving the slidable support, and means individual to the support, the breaking down means and the second recited means for individually controlling them.

100

76. In a machine of the class described, the combination of a reciprocable support, means mounted thereon for making a horizontal cut, means oscillatably mounted on the carriage for making a vertical cut, automatic means for oscillating the last said means, and means for varying the extent of said oscillating movement while one limit in the oscillating movement remains constant.

105

110

115

120

125

77. In a machine of the class described, the combination of a reciprocable support, means mounted thereon for making a hori-

130

zontal cut, means oscillatably mounted on the carriage for making a vertical cut, automatic means for oscillating the last said means, and means for varying the extent of 5 said oscillating movement while one limit of the oscillating movement remains constant.

78. In a mining machine, the combination with cutting mechanism, of means for 10 holding said cutting mechanism against movement in feeding direction, apparatus for storing power in said cutting mechanism, an appliance for releasing said holding means when said apparatus tends to move 15 said cutting mechanism in feeding direction, and a device for effecting the operation of said cutting mechanism.

79. In a machine of the class described, the combination of a main support, a sliding support thereon, an endless flexible cutter on the sliding support for making a horizontal cut, a cutter for making a vertical cut oscillatably mounted on the sliding support for continuous cutting operation, 25 means for oscillating the cutter positively in both directions, means for varying the degree of such oscillating movement while one limit of such movement remains constant, and breaking down means on the 30 sliding support, operating above the first said cutter.

80. In a machine of the class described, the combination of a plurality of oscillatable cutters for making vertical cuts, means 35 for oscillating the cutters, means for varying the degree of oscillating movement of the cutters while one limit of such movement remains constant, breaking down means operating between the planes of operation of the said cutters, and a conveyer operating below the breaking down means.

81. In a machine of the class described, the combination of a plurality of oscillatable cutters for making vertical cuts, means 45 for oscillating the cutters, means for varying the degree of oscillating movement of the cutters while one limit of such movement remains constant, breaking down means operating between the planes of operation of the said cutter, a conveyer operating below the breaking down means, and means individual to the said cutters for controlling them.

82. In a machine of the class described, 55 the combination of a main support, a sliding support thereon, a horizontal groove cutter mounted on the sliding support, a plurality of oscillatable cutters for making vertical cuts, means for oscillating the cutters, means for varying the degree of oscillating movement of the vertical cutters while one point in such movement remains constant, breaking down means operating between the plane of operation of the said

vertical cutters, and a conveyer operating 65 below the breaking down means.

83. In a machine of the class described, the combination of a main support, a sliding support thereon, a horizontal groove cutter mounted on the sliding support, a 70 plurality of oscillatable cutters for making vertical cuts, means for oscillating the cutters, means for varying the degree of oscillating movement of the vertical cutters while one point in such movement remains 75 constant, breaking down means operating between the plane of operation of the said vertical cutters, and a conveyer on said sliding support.

84. In a machine of the class described, 80 the combination of a plurality of oscillatable cutters for making vertical cuts, means for oscillating the cutters, reciprocating breaking down means independent of said cutters and mounted for pivotal movement 85 upwardly and downwardly to operate within the planes of operation of the vertical cutters, and means for reciprocating the breaking down means, the last said means also operating to impart a pivotal movement 90 to the breaking down means.

85. In a machine of the class described, the combination of a plurality of oscillatable cutters for making vertical cuts, means for oscillating the cutters, reciprocating 95 breaking down means independent of said cutters and mounted for pivotal movement upwardly and downwardly to operate within the planes of operation of the vertical cutters, means for reciprocating the breaking down means, the last said means also operating to impart a pivotal movement to the breaking down means, and a conveyer operating below the said breaking down means.

86. In a machine of the class described, the combination of a plurality of oscillatable cutters for making vertical cuts, means for oscillating the cutters, reciprocating breaking down means independent of said 110 cutters and mounted for pivotal movement upwardly and downwardly to operate within the planes of operation of the vertical cutters, means for reciprocating the breaking down means, the last said means also 115 operating to impart a pivotal movement to the breaking down means, and means for preventing the pivotal movement of said breaking down means under the influence of the operating means of the latter.

87. In a machine of the class described, the combination of a plurality of oscillating cutters for making vertical cuts, means for oscillating the cutters, reciprocating breaking down means independent of said 125 cutters and mounted for pivotal movement upwardly and downwardly to operate within the planes of operation of the vertical

cutters, means for reciprocating the breaking down means, the last said means also operating to impart a pivotal movement of the breaking down means, and a conveyor operating below the said breaking down means.

88. In a machine of the class described, the combination of a main supporting frame, a carriage slidably mounted thereon, said carriage embodying sections connected for relative movement, an endless flexible cutter connected with said sections and adapted to make a horizontal cut, means for relatively adjusting the carriage sections whereby the said cutter will be tightened or loosened, a vertical cutter on the carriage, breaking down means also on the carriage and operating above the horizontal cutter, and means for reciprocating the carriage on the support.

89. In a machine of the class described, the combination of a main supporting frame, a carriage slidably mounted thereon, said carriage embodying sections connected for relative movement, an endless flexible cutter connected with said sections and adapted to make a horizontal cut, means for relatively adjusting the carriage sections whereby the said cutter will be tightened or loosened, a vertical cutter on the carriage, breaking down means also in the carriage and operating above the horizontal cutter, an endless conveyer in the carriage operating below the breaking down means, and means for reciprocating the carriage on the support.

90. In a machine of the class described, the combination of a main supporting frame, a carriage slidably mounted thereon, said carriage embodying sections connected for relative movement, an endless flexible cutter connected with said sections and adapted to make a horizontal cut, means for relatively adjusting the carriage sections and maintaining them in their adjusted position whereby the said cutter will be tightened or loosened, a vertical cutter on the carriage, breaking down means also in the carriage and operating above the horizontal cutter, and means for reciprocating the carriage on the support.

91. In a machine of the class described, the combination of a main support, a carriage reciprocably mounted thereon, feeding mechanism for feeding the carriage forwardly and rearwardly at different rates of speed, means for manually controlling such feeding mechanism from either side of the machine, means for also controlling such feeding mechanism automatically, an oscillatable cutter on the carriage, breaking down means also oscillatably mounted on the carriage and movable independently of said cutter.

92. In a machine of the class described,

the combination of a main support, a carriage reciprocably mounted thereon, feeding mechanism for feeding the carriage forwardly and rearwardly at different rates of speed, means for manually controlling such feeding mechanism from either side of the machine, means for also controlling such feeding mechanism automatically, an oscillatable cutter on the carriage, breaking down means also oscillatably mounted on the carriage and movable independently of the said cutter, means for oscillating the cutter, and means for varying the degree of oscillation of the said cutter while one limit of such movement remains constant.

93. In a machine of the class described, the combination of a main support, a carriage reciprocably mounted thereon, feeding mechanism for feeding the carriage forwardly and rearwardly at different rates of speed, means for manually controlling such feeding mechanism from either side of the machine, means for also controlling such feeding mechanism automatically, an oscillatable cutter on the carriage, breaking down means also oscillatably mounted on the carriage and movable independently of the said cutter, and an endless conveyer on the carriage extending beneath the cutter.

94. In a machine of the class described, the combination of a main support, a carriage reciprocably mounted thereon, feeding mechanism for feeding the carriage forwardly and rearwardly at different rates of speed, means for manually controlling such feeding mechanism from either side of the machine, means for also controlling such feeding mechanism automatically, an oscillatable cutter on the carriage, breaking down means also oscillatably mounted on the carriage and movable independently of the said cutter, an endless conveyer on the carriage extending beneath the cutter, and means for varying the degree of oscillating movement of the cutter while one limit of such movement remains constant.

95. In a machine of the class described, the combination of a main support, a carriage reciprocable thereon, means for feeding the carriage forwardly and rearwardly, means for controlling such feeding means, a cutter oscillatably mounted on the carriage to cut vertical cuts, an endless conveyer mounted on the carriage to extend beneath the cutter and bodily removable from the carriage as a unit, and breaking down means on the carriage operating above the said conveyer.

96. In a machine of the class described, the combination of a main support, a carriage reciprocable thereon, means for feeding the carriage forwardly and rearwardly, means for controlling such feeding means, a cutter oscillatably mounted on the carriage to cut vertical cuts, an endless con-

veyer mounted on the carriage to extend beneath the cutter and bodily removable from the carriage as a unit, and breaking down means oscillatably mounted on the carriage 5 operating above the said conveyer.

97. In a machine of the class described, the combination of a main support, a carriage reciprocable thereon, means for feeding the carriage forwardly and rearwardly, 10 means for controlling such feeding means, a cutter oscillatably mounted on the carriage to cut vertical cuts, an endless conveyer mounted on the carriage to extend beneath the cutter and bodily removable from the 15 carriage as a unit, and reciprocating breaking down means oscillatably mounted on the carriage and operating above the said conveyer.

98. In a machine of the class described, 20 the combination of a main support, a carriage reciprocably mounted thereon, a plurality of cutters for making vertical cuts, pivotally mounted upon the carriage for movement upwardly and downwardly, an 25 endless conveyer detachably mounted upon the carriage and extending beneath the said cutters, means for oscillating the cutters about their pivots, means individual to the cutters for independently controlling their 30 oscillating movement, and breaking down means also mounted upon the carriage independently of the cutters and operating above the conveyer and between the planes of operation of the cutters.

99. In a machine of the class described, 35 the combination of a main support, a carriage reciprocably mounted thereon, a plurality of cutters for making vertical cuts, pivotally mounted upon the carriage for 40 movement upwardly and downwardly, an endless conveyer detachably mounted upon the carriage and extending beneath the said cutters, means for oscillating the cutters about their pivots, means individual to the 45 cutters for independently controlling their oscillating movement, and reciprocating breaking down means also mounted upon the carriage independently of the cutters and operating above the conveyer and between the 50 planes of operation of the cutters.

100. In a machine of the class described, 55 the combination of a main support, a carriage reciprocably mounted thereon, a plurality of cutters for making vertical cuts, pivotally mounted upon the carriage for 60 movement upwardly and downwardly, an endless conveyer detachably mounted upon the carriage and extending beneath the said cutters, means for oscillating the cutters about their pivots, means individual to the cutters for independently controlling their oscillating movement, and reciprocating breaking down means mounted upon the carriage independently of the said cutters and

for pivotal movement upwardly and downwardly, said breaking down means operating between the planes of operation of the cutters and above the conveyer. 65

101. In a machine of the class described, the combination of a main support, a carriage reciprocably mounted thereon, a plurality of cutters for making vertical cuts, pivotally mounted upon the carriage for movement upwardly and downwardly, an 70 endless conveyer detachably mounted upon the carriage and extending beneath the said cutters, means for oscillating the cutters about their pivots, means individual to the cutters for independently controlling their oscillating movement, and reciprocating 75 breaking down means mounted upon the carriage independently of the said cutters and for pivotal movement upwardly and downwardly, said breaking down means operating between the planes of operation of the 80 cutters and above the conveyer, means for oscillating the cutters, and means for varying the degree of oscillating movement of the cutters while one limit of such movement remains constant. 90

102. In a machine of the class described, the combination of a main support, a carriage reciprocably mounted thereon, a plurality of cutters oscillatably mounted on the carriage for making vertical cuts, an endless conveyer 95 detachably mounted on the carriage and extending below the cutters, and reciprocating breaking down means also oscillatably mounted on the conveyer between the plane of operation of the said cutters. 100

103. In a machine of the class described, the combination of a main support, a carriage reciprocable thereon, a plurality of cutters oscillatably mounted on the carriage for making vertical cuts, an endless conveyer 105 detachably mounted on the carriage and extending below the cutters, reciprocating breaking down means pivotally mounted on the carriage to operate above the first said conveyer and between the plane of operation of the said cutters, and means for automatically feeding the breaking down means to the work and in one direction about its pivot. 110

104. In a machine of the class described, the combination of a main support, a carriage reciprocable thereon, a plurality of cutters oscillatably mounted on the carriage for making vertical cuts, an endless conveyer 115 detachably mounted on the carriage and extending below the cutters, reciprocating breaking down means pivotally mounted on the carriage to operate above the first said conveyer and between the plane of operation of the said cutters, and means for automatically feeding the breaking down means to the work and in one direction about its pivot, said breaking down 120

125

means being adapted for free movement about its pivot in the opposite direction by gravity.

105. In a machine of the class described, 5 the combination of a main support, a carriage reciprocable thereon, a plurality of cutters oscillatably mounted on the carriage for making vertical cuts, an endless conveyer detachably mounted on the carriage 10 and extending below the cutters, reciprocating breaking down means pivotally mounted on the carriage to operate above the first said conveyer and between the plane of operation of the said cutters, and means 15 for automatically feeding the breaking down means to the work and in one direction abouts its pivot, said breaking down means being adapted for free movement about its pivot in the opposite direction by 20 gravity, and means for rendering the said feeding means inactive and for maintaining the breaking down means in any of its adjusted positions.

106. In a machine of the class described, 25 the combination of a main support, a carriage reciprocable thereon, a plurality of cutters oscillatably mounted on the carriage for making vertical cuts, an endless conveyer detachably mounted on the carriage 30 and extending below the cutters, reciprocating breaking down means pivotally mounted on the carriage to operate above the first said conveyer and between the plane of operation of the said cutters, and means 35 for automatically feeding the breaking down means to the work and in one direction about its pivot, said breaking down means being adapted for free movement about its pivot in the opposite direction by 40 gravity, and means under the control of the operator for rendering the said feeding means inactive and for maintaining the breaking down means in any of its adjusted positions.

45 107. In a mining machine, the combination with a support, of a reciprocating tool mounted thereon, means for operating said tool, a slide reciprocably mounted on said support, latch mechanism, means for reciprocating said slide and for retracting said tool through said latch mechanism, means for releasing said latch mechanism to cause said tool operating means to act, and means for automatically resetting said latch 50 mechanism for the next retracting movement.

108. In a machine of the class described, 55 the combination of a support, a reciprocating tool supported thereby, means for forcing the tool forwardly into engagement with the work, a slide reciprocably supported by the support, means for reciprocating the slide, a pivoted pawl operatively related to the tool and slide and adapted to

coöperate to retract the tool against the stress 65 of the first recited means when the slide is moved in one direction, and a limit stop engaging said pawl for releasing the tool when the slide reaches the limit of the re-tracting movement. 70

109. In a machine of the class described, 75 the combination of a support, a reciprocating tool supported thereby, means for forcing the tool forwardly into engagement with the work, a slide reciprocably supported by the support, means for reciprocating the slide, a pivoted pawl operatively related to the tool and slide and adapted to coöperate to retract the tool against the stress of the first recited means when the slide is moved 80 in one direction, a limit stop engaging said pawl for automatically releasing the tool when the slide reaches the limit of the re-tracting movement, and an additional limit stop engaging said pawl for resetting the 85 same.

110. In a mining machine, the combination 90 with a supporting frame, a plurality of spaced-apart picks extending longitudinally of said frame and mounted thereon to reciprocate relatively thereto, a plurality of springs mounted on said frame, one spring being associated with each of said picks, the rear ends of said picks each having longitudinal guide grooves, cylindrical abutments one pivoted at the rear portion of each of said picks to extend respectively into said grooves a short distance ahead of the rear end of said pick, a slide reciprocably mounted on the rear portion of said frame 95 and on the rear portions of said picks, a plurality of pivoted pawls carried by said slide in spaced-apart positions respectively in upright planes extending through said grooves and said cylindrical abutments, means for moving said slide rearwardly 100 while said pawls engage said cylindrical abutments to effect rearward movement of said picks to compress said springs, fixed abutments carried by the rear end of said frame in position to engage the respective pawls to trip the same to release said picks 105 to cause said springs to actuate said picks percussively, said slide-moving means being also capable of moving the slide forwardly 110 to initial position, and additional abutments spaced forwardly of said fixed abutments in position to engage the respective pawls and reset the same by causing them to move 115 into said grooves in position for reengaging said cylindrical abutments. 120

111. In a machine of the class described, 125 the combination of a support, a tool reciprocably mounted thereon, means for forcing the tool forwardly into engagement with the work, a slide reciprocably supported by the said support, means for reciprocating the slide, a catch on the slide, means connected

with the tool and with which the catch co-operates for retracting the tool, means for automatically disconnecting the slide and tool at the limit of the retracting movement, 5 and means for locking the tool in its retracted position.

112. In a machine of the class described, the combination of a support, a tool reciprocably mounted thereon, means for forcing 10 the tool forwardly into engagement with the work, a slide reciprocably supported by the said support, means for reciprocating the slide, a catch on the slide, means connected with the tool and with which the 15 catch co-operates for retracting the tool, means for automatically disconnecting the slide and tool at the limit of the retracting movement, and means for locking the tool in its retracted position and at will.
113. In a machine of the class described, the combination of a support, a reciprocating tool mounted thereon, means for forcing the tool forwardly into engagement with the work, a slide supported by the said 25 support, means for reciprocating the slide, a pawl rotatably mounted upon the slide, means connected with the tool and with which the pawl co-operates to retract the tool, and automatic means for shifting the 30 catch with respect to the slide and move the pawl into and out of operative positions.

114. In a machine of the class described, the combination of a pivotally mounted support, a cutter reciprocably mounted thereon, 35 means for forcing the cutter forwardly and into engagement with the work, a supplemental support mounted upon the first said support for movement forwardly and backwardly, operating means for the supplemental support, and means whereby each movement of the supplemental support in one direction will retract the cutter, the said operating means also operating when the cutter is being retracted to shift the first 45 said support about its pivot.

115. In a machine of the class described, the combination of a pivotally mounted support, a cutter reciprocably mounted thereon, means for forcing the cutter forwardly and 50 into engagement with the work, a supplemental support mounted upon the first said support for movement forwardly and backwardly, operating means for the supplemental support, means whereby each movement of the supplemental support in one direction will retract the cutter, the said operating means also operating when the cutter is being retracted to shift the first said support about its pivot, and means for causing the 55 said operating means to retract the cutter one or more times without shifting the first said support.

116. In a machine of the class described, the combination of a pivotally mounted support, a cutter reciprocably mounted thereon, 65

resilient means for forcing the cutter forwardly and into engagement with the work, a supplemental support mounted upon the first said support for forward and backward movement, operating means for the supplemental support, and means whereby the backward movement of the support will retract the cutter to exert stress upon the said resilient means, said stress operating to cause the said operating means to move the first 75 said support.

117. In a machine of the class described, the combination of a pivotally mounted support, a cutter reciprocably mounted thereon, resilient means for forcing the cutter forwardly and into engagement with the work, a supplemental support mounted upon the first said support for forward and backward movement, operating means for the supplemental support, means whereby the 80 backward movement of the support will retract the cutter to exert stress upon the said resilient means, and means whereby the said stress will intermittently move the first said support about its pivot, upon each retracting 85 movement of the cutter.

118. In a machine of the class described, the combination of a pivotally mounted support, a cutter reciprocably mounted thereon, resilient means for forcing the cutter forwardly and into engagement with the work, a supplemental support mounted upon the first said support for forward and backward movement, operating means for the supplemental support, means whereby the 90 backward movement of the support will retract the cutter to exert stress upon the said resilient means, means whereby the said stress will intermittently move the first said support about its pivot upon each retracting 95 movement of the cutter, and means for causing the said cutter to be retracted one or more times without moving the first said support.

119. In a machine of the class described, the combination of a pivotally mounted support, a cutter reciprocably mounted thereon, resilient means for forcing the cutter forwardly and into engagement with the work, a supplemental support mounted upon the 100 first said support for forward and backward movement, operating means for the supplemental support, means whereby the backward movement of the support will retract the cutter to exert stress upon the said resilient means, means whereby the said stress will intermittently move the first said support about its pivot upon each retracting 105 movement of the cutter, and means under the control of the operator for causing the 110 said cutter to be retracted one or more times without moving the first said support.

120. In a mining machine, the combination with a main supporting frame, of a supplemental frame mounted for up and down 115

oscillating movement on said main frame, breaking-down means carried by said supplemental frame, means for operating said breaking-down means, means for intermittently moving the supplemental frame in one direction embodying a toothed element carried by one of said frames, a ratchet element carried by the other frame to coöperate with such toothed element, and means for actuating the ratchet element to release the supplemental frame.

121. In a machine of the class described, the combination of breaking down means, means for feeding the same to the work, embodying a fixed and a movable element, ratchet teeth carried by one of the elements, oppositely disposed ratchet members carried by the other element and operating simultaneously in the same space between the ratchet teeth, means for retracting said ratchet members separately to release the movable element, and means for moving the movable element when thus released.

122. In a machine of the class described, the combination of breaking down means, means for feeding the same to the work, embodying a fixed and a movable element, ratchet teeth carried by one of the elements, oppositely disposed ratchet members carried by the other element and operating simultaneously in the same space between the ratchet teeth, means for automatically retracting said teeth to release the movable element, and means for moving the movable element in a feeding direction when one of said ratchet members is retracted.

123. In a machine of the class described, the combination of breaking down means, means for feeding the same to the work, embodying a fixed and a movable element, ratchet teeth carried by one of the elements, oppositely disposed ratchet members carried by the other element and operating simultaneously in the same space between two teeth for respectively locking the breaking down means against feeding and return movement, and means for automatically withdrawing one of the ratchet elements to permit a feeding movement.

124. In a machine of the class described, the combination of breaking down means, means for feeding the same to the work, embodying a fixed and a movable element, ratchet teeth carried by one of the elements, oppositely disposed simultaneously in the same space between two teeth for respectively locking the breaking down means against feeding and return movement, means for locking the said ratchet element when thus withdrawn, and during the said feeding movement, and means for unlocking said ratchet element.

125. In a machine of the class described, the combination of breaking down means, means for feeding the same to the work,

embodying a fixed and a movable element, ratchet teeth carried by one of the elements, oppositely disposed ratchet members carried by the other element and operating simultaneously in the same space between two teeth for respectively locking the breaking down means against feeding and return movement, tappet mechanism for withdrawing one of the ratchet elements to permit a feeding movement, means for locking the said element when thus withdrawn and during said feeding movement, and means for unlocking said ratchet element.

126. In a machine of the class described, the combination of breaking down means, means for feeding the same to the work, embodying a fixed and a movable element, ratchet teeth carried by one of the elements, oppositely disposed ratchet members carried by the other element and operating simultaneously in the same space between two teeth for respectively locking the breaking down means against feeding and return movement, means for automatically withdrawing one of the ratchet elements to permit a feeding movement, means for locking said ratchet element when thus withdrawn and during the said feeding movement, and means whereby the other ratchet element will unlock the first said ratchet element.

127. In a machine of the class described, the combination of breaking down means, means for feeding the same to the work, embodying a fixed and a movable element, ratchet teeth carried by one of the elements, oppositely disposed ratchet members carried by the other element and operating simultaneously in the same space between two teeth for respectively locking the breaking down means against feeding and return movement, means for automatically withdrawing one of the ratchet elements to permit a feeding movement, means for locking said ratchet element when thus withdrawn and during the said feeding movement, and means whereby the said feeding movement will cause the other ratchet element to unlock the said locked element.

128. In a machine of the class described, the combination of breaking down means, means for feeding the same to the work, embodying a fixed and movable element, ratchet teeth carried by one of the elements, oppositely disposed ratchet members carried by the other element and operating simultaneously in the space of the same two teeth for respectively locking the movable element against feeding and return movements, means for automatically withdrawing one of the ratchet elements to release the movable element for feeding movement, means for locking said ratchet element in its retracted position, means whereby the other ratchet element will render the locking means ineffective by the feeding movement of the

movable element, one of said ratchet elements being carried by the other.

129. In a machine of the class described, the combination of breaking down means, 5 means for feeding the same to the work, embodying a fixed and a movable element, ratchet teeth carried by one of the elements, oppositely disposed ratchet members carried by the other element and operating simultaneously in the space of the same two teeth, for respectively locking the movable element against feeding and return movements, means for automatically withdrawing one of the ratchet elements to release the movable 10 element for feeding movement, means for locking said ratchet element in its retracted position, means whereby the other ratchet element will render the locking means ineffective by the feeding movement of the 15 movable element, and means for rendering both of said ratchet elements inactive.

130. In a machine of the class described, the combination of breaking down means, means for feeding the same to the work, embodying a fixed and a movable element, 20 ratchet teeth carried by one of the elements, oppositely disposed ratchet members carried by the other element and operating simultaneously in the space of the same two teeth 25 for respectively locking the movable element against feeding and return movements, means for automatically withdrawing one of the ratchet elements to release the movable element for feeding movement, means 30 for locking said ratchet element in its retracted position, means whereby the other ratchet element will render the locking means ineffective by the feeding movement of the movable element, and manual means 35 for rendering both of said ratchet elements inactive.

131. In a machine of the class described, the combination of breaking down means, means for feeding the same to the work, embodying a fixed and movable element, 40 ratchet teeth carried by one of the elements, oppositely disposed ratchet members carried by the other element and operating simultaneously in the space of the same two teeth 45 for respectively locking the movable element against feeding and return movements, means for automatically withdrawing one of the ratchet elements to release the movable element for feeding movement, means for locking said ratchet element in its retracted position, means whereby the other ratchet element will render the locking means ineffective by the feeding movement of the 50 movable element, said ratchet elements being connected for independent movement and for movement together, and means for imparting the last recited movement to the ratchet elements.

132. In a machine of the class described, 55 the combination of breaking down means,

means for feeding the same to the work, embodying a fixed and a movable element, ratchet teeth carried by one of the elements, oppositely disposed ratchet members carried by the other element and operating simultaneously in the space of the same two teeth 70 for respectively locking the movable element against feeding and return movements, means for automatically withdrawing one of the ratchet elements to release 75 the movable element for feeding movement, means for locking said ratchet element in its retracted position, means whereby the other ratchet element will render the locking means ineffective by the feeding movement 80 of the movable element, said ratchet elements being connected for independent movement and for movement together, and means for imparting the last recited movement to the ratchet elements and at will. 85

133. In a mining machine, the combination with cutting mechanism, of means for operating the same, apparatus for storing power in said operating means until said cutting mechanism starts to be moved in 90 feeding direction, means for holding the cutting mechanism against feeding movement, a device for releasing said holding means after power has been stored in said operating means, and apparatus for making said holding means effective in a new position after 95 said cutting mechanism has been operated.

134. In a mining machine, the combination with a reciprocating pick, of a spring 100 for actuating the same, a main frame, a supplemental frame pivoted to said main frame and carrying said pick and said spring, means mounted on said main and supplemental frames for storing power in said spring, mechanism for holding said supplemental frame against movement while power is being stored in said spring, a device for releasing said holding means to effect movement of said supplemental frame and appliances for releasing said spring after said 110 supplemental frame has been moved to a new position.

135. In a mining machine, the combination with a reciprocating pick, of a spring 115 for actuating the same, means for storing power in said spring and tending to move the pick in feeding direction, a toothed member connected to said pick and forming a series of spaced apart notches, a latch adapted to extend into any one of said notches 120 to hold the pick against feeding movement when power is being stored in said spring, means for releasing said latch, a device for locking said latch in a released position, a means for unlocking said latch after movement of said pick in feeding direction, and means for releasing said spring to actuate said pick.

136. In a mining machine, the combination with a pick machine comprising a pick, 125

5 a frame, and a spring for actuating said pick, of means tending to move said frame in feeding direction for storing power in said spring, a toothed member connected to said frame, latch mechanism coöperating with said toothed member to hold said frame against feeding movement, means for releasing said latch mechanism to permit feeding movement of said frame, and appliances for
10 releasing said spring to actuate said pick.

137. In a mining machine, the combination with breaking down mechanism comprising a reciprocating tool, a spring and a frame, of means for storing power in said spring, a toothed member connected to said frame, a latch engaging said toothed member to hold the frame against feeding movement, means for releasing said latch to cause said stored power to move said frame in feeding direction, a device for locking said latch in released position, mechanism acted on by said toothed member to unlock said latch after the engaging of said feeding movement, and means for effecting the release of said spring to actuate said tool.

138. In a mining machine, the combination with breaking-down mechanism, of a toothed member connected thereto and movable bodily therewith, reversely arranged latch mechanism associated with said toothed member for holding the breaking-down mechanism against movement in either direction, means for operating said breaking-down mechanism, and apparatus for securing feeding movements step by step in the same direction at recurring intervals of said breaking-down mechanism by control of said latch mechanism.

139. In a mining machine, the combination with cutting mechanism, of means for operating the same, apparatus for controlling the feed of said cutting mechanism to secure a step by step movement thereof at recurring intervals, said feeding apparatus comprising a toothed member and reversely arranged mechanism for holding the cutting mechanism against movement in either direction between such feeding intervals, and means for entirely releasing said mechanism to permit free movement of said cutting mechanism in the opposite direction.

140. In a mining machine, the combination with cutting mechanism, of means for operating the same, feeding apparatus for said cutting mechanism comprising a toothed member, a latch for engaging said toothed member to hold the cutting mechanism against feeding movement, means for releasing said latch, a device for locking said latch in released position, and an additional latch for holding said cutting mechanism against reversed movement and acting against a tooth of said member to release said locking device.

141. In a mining machine, the combina-

tion with cutting mechanism, of means for operating same, apparatus for feeding said cutting mechanism comprising a toothed member, a latch for engaging said toothed member to hold said cutting mechanism against the feeding movement, an additional latch for simultaneously holding said cutting mechanism against reversed movement, and manual mechanism for releasing both of said latches.

142. In a mining machine, the combination with a reciprocating pick, of a spring for actuating the same, a pivoted frame carrying said pick and spring, a toothed member connected to said frame, means tending to move said pick in feeding direction for storing power in said spring, a latch connected to said toothed member to hold the same against feeding movement, means for automatically releasing said latch after power has been stored in said spring to a predetermined extent, to effect step feeding movements of said pick, and mechanism for releasing said spring to actuate said pick.

143. In a mining machine, the combination with a reciprocating pick, of a spring for actuating the same, a pivoted frame carrying said pick and spring, a toothed member connected to said frame, reversely arranged latches connected to said member, one to hold said frame against feeding movement and the other to hold it against reversed movement, means for storing power in said spring until after it tends to move said frame in feeding direction, pawl mechanism for releasing the feed latch to permit said power storing means to move said frame a step in feeding direction, a device acting on said pawl mechanism to lock said feed latch in released position until its notch has been moved away therefrom, and connections causing the reversed latch to unlock said locking device to permit said feed latch to snap into the next notch.

144. In a mining machine, the combination with a reciprocating pick, of a spring for actuating the same, a pivoted frame carrying said pick and spring and tending to descend by gravity at the pick end, an arc-shaped member connected to said frame, a brake associated with said member, a series of spaced apart teeth carried by said member to form a series of notches, latch mechanism coöperating with said teeth to prevent upward movement of said pick, means for storing power in said spring, automatic apparatus for releasing the said latch mechanism to permit one step of movement of said pick in feeding direction, means for releasing said spring each time after such step feeding movement, means for releasing said latch mechanism to permit free movement of said frame downwardly by gravity, and a device for applying said

brake to retard such downward movement of said pick frame.

145. In a mining machine, the combination with a chain cutter for undercutting a body of coal, of a platform along the front and sides of which said chain-cutter is adapted to travel, and a conveyer having superposed portions traveling in opposite directions and extending to the forward portion of said platform and over substantially the entire width thereof between the side runs of said chain cutter to operate continuously substantially in the plane produced by said kerf cutter to carry dislodged material directly back from the mine wall while said conveyer and said platform extend into the kerf produced by said chain cutter.

146. In a mining machine, the combination with breaking down mechanism mounted for pivotal movement upwardly and downwardly, of automatic means for moving said breaking down mechanism about its pivot intermittently in the same direction, and means for rendering said automatic means inactive for permitting the breaking down mechanism to move about its pivot in the opposite direction and by gravity.

147. In a mining machine, the combination with a frame having an upright guideway, of a cutter mounted for movement along said guideway, means for reciprocating said cutter forwardly and rearwardly, and means for feeding said cutter upwardly along said guideway substantially at the end of each rearward stroke of said cutter.

148. In a mining machine, the combination with a frame or support having a guideway, of a cutter, means for raising said cutter along said guideway, means for reciprocating said cutter forward and backward, breaking means for holding said cutter in position, and means for releasing said breaking means to permit feeding of said cutter upwardly substantially at the end of each backward stroke.

149. In a mining machine, the combination with a frame or support having an upright guideway, of a cutter, means for raising said cutters along said guideway, means for reciprocating said cutter forward and backward, means for operating said raising mechanism to feed said cutter along said guideway, and means operable substantially at the end of each backward stroke of said cutter for setting said cutter-raising means in operation.

150. In a mining machine, the combination with a frame or support having an upright guideway, of a cutter, means for raising said cutter along said guideway, means for reciprocating said cutter, means for operating said raising mechanism to feed said cutter along said guideway, means for hold-

ing said cutter in position, and means operable substantially at the end of each backward stroke of said cutter for releasing said holding means and for setting said cutter-raising means in operation.

151. In a mining machine, the combination with a frame having a guideway, of a pick machine movable up and down along said guideway and mounted on said frame to have a tendency to descend by gravity to initial position, means for feeding said pick machine upwardly step by step, means for operating said pick machine, and means in position for throwing said feeding means out of operation in any position of said pick machine to cause the latter to move by gravity to initial position.

152. In a mining machine, the combination with a supporting frame having a guideway, of a multiple pick machine movable up and down along said guideway, means for feeding said pick machine, means for holding said pick machine in fixed position relatively to said guideway, intermittently operable controlling means for said feeding and holding means to automatically release said holding means and effect the feed of said pick machine, such feed being automatically alternated with the holding of said pick machine in successive fixed positions, and means in position for throwing said controlling means out of operation to free said pick machine for movement to initial position from any position to which it has been fed.

153. In a mining machine, the combination with a frame or support, of a guideway thereon, a cutter movable along said guideway, means for operating said cutter, means for feeding said cutter step by step along said guideway, means for locking said cutter relatively to said guideway, and means for releasing said feeding and locking means to effect movement of the cutter back to original position.

154. In a mining machine, the combination with a supporting frame, of a guideway thereon, a pick machine mounted on said frame to move along said guideway, means for feeding said pick machine step by step upwardly along said guideway, means for operating said pick machine during intervals alternating with the step by step feeding movements of said pick machine, and means for releasing said feeding means to effect automatic movement of said pick machine downwardly to initial position.

155. In a mining machine, the combination with a chain cutter, of a platform within the boundary of said chain cutter, means for operating said chain cutter, and an endless belt conveyer in said platform and movable therewith into the kerf produced by said chain cutter, said endless belt conveyer

being mounted in said platform transversely thereof and for operation longitudinally thereof directly back from the mine wall.

156. In a mining machine, the combination with an under-cutter and side kerf cutters, of means for effecting the simultaneous operation of said cutters, and an endless belt conveyer extending forwardly to a position within the boundary of the forward portion 10 of said under-cutter and laterally to positions near the side cutters, and operating directly back from the mine wall transversely to the forward run of said under-cutter to take substantially all of the dislodged material from the space between said side cutters and above said undercutter toward loading position.

157. In mining apparatus, the combination with a frame, of a platform extending 20 therefrom, an under-cutter carried by the peripheral forward portion of said platform, and an endless belt conveyer mounted on said platform to enter the kerf produced by said under-cutter together with said platform, said conveyer having superposed portions operating to and from said platform for taking back from the mine wall dislodged material.

158. In mining apparatus, the combination with a stationary frame, of a supplemental frame, a platform mounted on said supplemental frame, a kerf cutter operating about the forward portion of said platform, an endless belt conveyer having superposed 35 portions operating to and from said platform, and means for operating said kerf cutter including the feed of said supplemental frame, to cause said platform and the forward portion of said conveyer to enter 40 the kerf produced by said kerf cutter.

159. A mining machine comprising means for breaking down a section of a mine wall formed by an under-cut and spaced apart side cuts, in combination with loading 45 means extending into the under-cut and comprising an endless conveyer having superposed portions operating to and from the inner end of said under-cut.

160. In a mining and loading machine, 50 the combination with a stationary supporting frame, of a supplemental frame movable thereon, a rearwardly extending endless belt conveyer having superposed traveling portions mounted on said supplemental frame, an under-cutting kerf-cutter mounted on 55 said supplemental frame, means for feeding said supplemental frame forward to effect the operation of said under-cutter and move the forward portion of said conveyer into 60 the kerf produced by said under-cutter, and mechanism for dislodging the material above the under-cut onto said conveyer.

161. In a mining and loading machine, the combination with an under-cutting kerf-

cutter and spaced apart upright kerf cutters, an endless conveyer having superposed portions traveling into and out of the under-kerf, and means for dislodging the material above said under-cutter and between said side cutters onto said conveyer.

162. A mining and loading machine having kerf-producing means for cutting a substantially horizontal kerf at the base of the mine wall, in combination with a multiple percussive tool spanning the space above the 75 kerf between the lateral edges thereof to engage the material to be mined over such space and remote from such kerf to break down the material in lumps and so as not to enter said kerf.

163. In a mining and loading machine, the combination with kerf-cutting mechanism, of means for supporting said kerf-cutting mechanism in position for cutting a kerf at the base of the mine wall, a multiple 85 reciprocating tool spanning the space above said kerf between the lateral edges thereof to engage the material above said kerf and remote therefrom, and an endless conveyer having superposed portions traveling in opposite directions and adapted to extend into such kerf for receiving the material as it falls after detachment by said tool from such space and conveying such material 90 back from the mine wall.

164. In a mining and loading machine, the combination with an under-cutting kerf cutter, of spaced apart upright side kerf cutters, an endless conveyer of the belt type having superposed portions entering and emerging from the kerf produced by said undercutter to carry back from the mine wall dislodged material above said under-cutter and between said side cutters, and means operable at will for trimming material from the roof above the space occupied by said dislodged material.

165. In a mining and loading machine, the combination with means for making a horizontal cut, of means for making spaced apart vertical cuts, and a conveyer having superposed portions entering and emerging from said horizontal cut for removing material broken down of its own weight above said horizontal cut and by the said side vertical cuts.

166. In a mining and loading machine, the combination with means for making a horizontal cut, of means for making spaced apart upright cuts, a conveyer having superposed portions entering and emerging from said horizontal cut for removing material broken down of its own weight above said horizontal cut and between said upright cuts, and a pick machine operable to remove 120 material from the roof between the planes of said spaced apart upright cutters.

167. In a mining and loading machine,

the combination with a stationary frame, of a support slidable thereon, means mounted on said slidable support for making a horizontal cut, means also mounted on said slid-
5 able support for making spaced apart vertical cuts, means for breaking down the material above said horizontal cut and between said side vertical cuts, a conveyer on said slidable support in position for receiving broken down material, and means for operating said conveyer.

168. In a mining and loading machine, the combination with a main frame, of a support slidable thereon, means on said 15 slidable support for making a horizontal cut, means on said slidable support for making spaced apart vertical cuts, a multiple pick machine mounted on said slidable support and operable between the planes of 20 said vertical cutting means, and a conveyer on said slidable support for operating below said multiple pick machine for receiving the material dislodged thereby.

169. In a mining and loading machine, 25 the combination with means for undercutting the plane kerf at the base of a mine wall, of mechanism for cutting spaced apart upright kerfs adjacent the lateral edges of said under kerf, a conveyer extending into 30 the under kerf, and means for operating said conveyer with the extended portion thereof continuously in said under kerf and in the plane thereof.

170. In a mining and loading machine, 35 the combination with a plurality of cutters for making spaced apart upright cuts, of means for operating said cutters, a multiple pick machine independent of said cutters and mounted for pivotal movement up- 40 wardly and downwardly to operate between the planes of operation of said upright cutters, and a conveyer operating below the said multiple pick machine.

171. In a mining and loading machine, 45 the combination with a main support, of a carriage reciprocable thereon, means for feeding the carriage forwardly and rearwardly, means on said carriage for making a horizontal kerf, means mounted on said 50 carriage for making spaced apart upright kerfs, and an endless conveyer mounted on said carriage to extend into the horizontal kerf, and bodily removable from the carriage as a unit.

55 172. In a mining and loading machine, the combination with a supporting frame, of means mounted thereon for making a horizontal kerf, means mounted on said supporting frame for making spaced apart 60 upright kerfs and an endless conveyer mounted on said frame to extend into the horizontal carriage, and bodily removable from the frame as a unit.

173. In a mining and loading machine, 65 the combination with an undercutting kerf

cutter, of spaced apart upright kerf cutters, means for operating said kerf cutters, and an endless conveyer detachably mounted and extending into the kerf produced by said under-cutter.

174. In a mining and loading machine, the combination with a main support, of a carriage reciprocable thereon, a plurality of cutters on said carriage for making vertical cuts, an endless conveyer detachably 75 mounted on said carriage, and means for dislodging material between the said vertical cuts directly onto said endless conveyer.

175. In a mining machine, the combination with breaking down mechanism mounted for up and down movement, of automatic means for giving said breaking down mechanism a short upward feeding movement, means for releasing the feeding mechanism, means for holding the breaking down mechanism in its upper position while said feeding mechanism is released, and means for operating said breaking down mechanism to effect dislodgment of material from the roof of a mine chamber while being held in its upper position, said holding means being removable to cause said breaking down mechanism to move downward by gravity to a position for a repetition of the aforesaid operation of upward feed and actuation of the breaking down mechanism.

176. In a mining machine, the combination with breaking down mechanism mounted for up and down movement, of automatic means for giving said breaking down mechanism a short upward feeding movement over any portion of its travel between the floor and the roof of the mine chamber, means for releasing said feeding means to permit said breaking down mechanism to recede by gravity to a lower position, means for holding said breaking down mechanism in any position along its path of travel between the floor and the roof of the mine chamber, and means for operating the 110 breaking down mechanism successively at approximately any desired portion of the space between the floor and the roof of the mine chamber.

177. In a mining and loading machine, 115 the combination with kerf-cutting mechanism for cutting a U-shaped kerf in a mine wall, of means for operating said kerf-cutting mechanism, a conveyer having a fixed and predetermined relation to said kerf-cutting mechanism, and bodily movable therewith in position to receive material dislodged within the boundary of said kerfs and means for continuously operating said conveyer to take back from the mine wall 125 the material as fast as dislodged.

178. In a mining and loading machine, the combination with kerf-cutting mechanism for cutting a U-shaped kerf in a mine wall, of means for operating said kerf-cut- 130

ting mechanism, a conveyer having superposed traveling portions in a position adjacent a part of said kerf-cutting mechanism to receive material directly thereon as dislodged from the space bounded by said kerfs, and means for operating said conveyer to remove the dislodged material from the mine wall.

179. In a mining and loading machine, the combination with kerf-cutting mechanism for cutting a U-shaped kerf in a mine wall, of means for operating said kerf-cutting mechanism, an endless conveyer mounted to have superposed traveling portions and in position to receive substantially all of the material dislodged from the space bounded by said kerfs, and means for operating said conveyer to move the dislodged material toward loading position.

180. In a mining and loading machine, the combination with kerf-cutting mechanism for cutting a U-shaped kerf in a mine wall, of means for operating said kerf-cutting mechanism, an endless conveyer mounted adjacent a portion of said kerf-cutting mechanism and in position to receive directly thereon material as dislodged from the space bounded by said kerfs, and breaking down mechanism operable on the body of material bounded by said kerfs to dislodge the material onto said conveyer.

181. In a mining and loading machine, the combination with a plurality of kerf-cutters operated simultaneously to produce a U-shaped kerf in a mine wall, of an endless conveyer following said kerf-cutters in position to receive dislodged material directly thereon, and means for operating said kerf-cutters and said endless conveyer to effect dislodgment of the material bounded by said kerfs and its removal from the mine wall toward loading position as soon as dislodged.

182. In a mining and loading machine, the combination with a main frame, of an inverted U-shaped supplemental frame pivotally connected on a substantially horizontal axis to the rear portion of said main frame to span the latter transversely, a multiple pick machine mounted on said supplemental frame to span said main frame transversely and to operate on a mine wall between the floor and roof of the mine chamber in advance of said main frame, and conveyer mechanism mounted on said main frame and extending from a receiving position near the range of operation of said pick machine longitudinally of said main frame to carry dislodged material from the mine wall through the U-shaped opening of said supplemental frame toward loading position.

183. In a mining and loading machine, the combination with a supporting frame, of an endless conveyer mounted longitudinally of said frame and having superposed portions traveling in opposite directions to

and from a receiving position at the forward portion of said frame, dislodging mechanism mounted on said frame for up and down movement at the mine wall between the floor and roof of a mine chamber and in advance of said frame, and means for supporting the dislodging mechanism to span the conveyer to provide a large open space between the conveyer and the dislodging mechanism for the passage of material carried by said conveyer under the dislodging mechanism and to the rear end of said frame.

184. In a mining and loading machine, the combination with a supporting frame, of an endless conveyer mounted longitudinally of said frame and inclined upwardly toward the rear from a receiving position at the forward portion of said frame, a multiple pick machine, a bifurcated frame for carrying said pick machine and pivotally connecting the same to said frame to span said conveyer while leaving a large open space beneath the pick machine for the passage of material carried by said conveyer to the rear end of said frame, means for continuously operating said conveyer to carry the dislodged material longitudinally of said supporting frame beneath said pick machine and through said bifurcated frame to the rear of said supporting frame, and means for operating said pick machine from a substantially horizontal position near the roof of the mine chamber to the base of the mine wall adjacent the receiving end of said conveyer.

185. In a mining and loading machine, the combination with a main frame, of an endless conveyer mounted on said main frame and having superposed portions traveling in opposite directions from a receiving position at the forward end of said frame near the floor of the mine chamber on an upward incline toward the rear of said frame, a bifurcated supplemental frame pivotally connected to the rear portion of said main frame on opposite sides of said conveyer and spanning said conveyer a substantial distance above the same to afford free passage of material carried by said conveyer, a pick machine carried by said bifurcated supplemental frame and extending forwardly from the upper spanning cross piece thereof for operation between the floor and roof of the mine chamber above the receiving end of said conveyer, and counterbalancing mechanism mounted on said main frame and connected to said bifurcated frame to counteract gravity acting on said pick machine.

186. In a mining and loading machine, the combination with a main frame having a longitudinal chute inclined toward the mine floor at its forward portion and extending on an upward incline toward the rear end of said frame, of an endless conveyer extending longitudinally of said chute, a bifurcated

supplemental frame pivotally connected to said main frame to span said chute and conveyer while affording an unobstructed opening through said bifurcated frame for the 5 passage of material conveyed along such chute by said conveyer, a multiple pick machine spanning the space above said chute and conveyer and connected to said bifurcated frame for tilting movement therewith, 10 and means for operating said multiple pick machine to dislodge material from a mine wall directly onto said conveyer.

187. In a mining and loading machine, the combination with a supporting frame, of an 15 endless conveyer mounted longitudinally of said frame and extending from a forward receiving position near the floor of the mine chamber on an upward incline toward the rear of said frame, a multiple pick machine 20 pivotally connected to the rear portion of said frame to span the space above said conveyer while affording an unobstructed space beneath the same for the passage of dislodged material along said frame toward 25 loading position, and resilient means mounted on said frame and connected to said pick machine near its pivotal connection to said frame for sustaining a portion of the weight of the forwardly extending pick machine.

188. In a mining and loading machine, the combination with a main support, of a conveyer extending longitudinally of said main support, dislodging mechanism comprising a support pivotally connected adjacent one 35 extremity with said main support, resilient means adjacent the pivot of the dislodging mechanism support for sustaining a portion of the weight of said dislodging mechanism, means for operating said dislodging mechanism to break down the material from a 40 mine wall onto said conveyer, and means for operating said conveyer to carry the dislodged material rearwardly through an unobstructed passageway below said dislodging mechanism and through the pivotal support thereof.

189. In a mining and loading machine, the combination with spaced-apart side kerf-cutters, of an under kerf-cutter spanning the 50 space between the planes of said side-kerf-cutters, a supporting frame for said cutters, an endless conveyer mounted longitudinally of said frame and extending from a receiving position approximately in the plane of 55 the kerf produced by the under kerf-cutter, on an upward incline to the rear portion of said frame, a motor mounted under the rear portion of said conveyer at the rear portion of said frame, dislodging mechanism mounted 60 on said frame above said conveyer for operation between the side kerfs and above the under kerf, and power transmission mechanism mounted on said frame ahead of said motor and partly under said conveyer

for operating said side kerf-cutters and said 65 under kerf-cutter and said dislodging mechanism.

190. In a machine of the character described, the combination with means for making a horizontal kerf in the material to 70 be mined, of means for making a vertical kerf, means acting in a plane transverse to one of said kerfs for breaking down the material, and means for automatically changing the position of such breaking-down 75 means intermittently.

191. In a mining machine, the combination with a base member, of means for cutting a horizontal groove in the material to 80 be mined, rotary means for cutting a vertical groove, and picking means acting in a plane transverse to the horizontal groove for breaking down the material.

192. In a mining machine, the combination with a base, of a plurality of rotating 85 cutters arranged to cut parallel vertical grooves, horizontally disposed cutting means arranged to cut a groove intersecting said vertical grooves, a reciprocable picking device arranged between said vertical cutters, 90 and a motor operably connected to each of said cutters and picking device.

193. In a mining machine, the combination with a base, of a carriage movable on said base, a plurality of rotating cutters 95 movable on said carriage and arranged to cut parallel grooves in the material to be mined, horizontally disposed cutting means mounted on the base and arranged to cut a groove intersecting said vertical grooves, and means for breaking down the material between said vertical grooves. 100

194. In a machine of the character described, the combination with a stationary base, of a carriage reciprocable on said base, 105 means for feeding the carriage toward and away from the material to be mined, an oscillatory frame mounted on said carriage, rotary cutters carried at the outer swinging end of said frame, means for oscillating said cutter frame, and means operating between the cutting planes of the cutters for breaking down the material. 110

195. The combination with a base member, of an endless chain traveling on said base 115 member, said chain being provided with grooving tools, a carriage reciprocably mounted on said base member, grooving tools mounted on said carriage and disposed at right angles to the plane of movement of 120 said endless chain, and means for oscillating said cutters toward and away from the endless chain.

196. In a machine of the character described, the combination with a base frame, 125 an endless chain grooving cutter operably mounted on said base frame, a carriage reciprocably mounted on said base frame, a

pair of rotary cutters oscillatably mounted on said carriage, and an endless chain conveyor mounted on said carriage.

197. In a machine of the character described, the combination with a base frame, of an endless chain grooving cutter movable on said frame, a carriage reciprocable on the base frame, grooving cutters oscillatably mounted on the carriage, and a picking device reciprocably mounted on said carriage.

198. In a machine of the character described, the combination with means for making a horizontal groove in the material to be mined, of means for grooving said material transversely to said horizontal groove, a supporting frame, and a picking device movable upwardly and downwardly on the frame for breaking down the material.

199. In a machine of the character described, the combination with means for making a horizontal groove in the material to be mined, of means for grooving said material transversely to said horizontal groove, a supporting frame, and a picking device movable upwardly and downwardly on the frame for breaking down the material, said picking device being reciprocably mounted.

200. In a machine of the character described, the combination with a pivoted cutter frame, of grooving cutters mounted thereon, a pick reciprocably mounted on said frame, said pick being provided with resilient means for driving it into the material to be mined, and means for moving the pick to compress the resilient means and for releasing said pick, said cutter frame being oscillatable about one end.

201. In a machine of the character described, the combination with a base member, of a carriage reciprocably mounted thereon, feeding mechanism for feeding said carriage forwardly and rearwardly at different rates of speed respectively, an oscillatable cutter mounted on said carriage, and an oscillatable picking device also mounted on said carriage.

202. In a machine of the class described, the combination of a main support, a cutter support oscillatably mounted thereon, a cutter on the cutter support for making vertical cuts, means for oscillating the cutter support, embodying means for varying the degree of oscillating movement of the cutter support while one limit of the oscillating movement of the cutter support remains constant, said oscillating means comprising a rotary element, and means between the rotary element and the said cutter frame, and having adjustable connection with both.

203. In a machine of the class described, the combination of a main support, a cutter support oscillatably mounted thereon, a cutter on the cutter support for making vertical cuts, means for oscillating the cutter support, em-

bodying means for varying the degree of oscillating movement of the cutter support while one limit of the oscillating movement of the cutter support remains constant, the said oscillating means comprising a rotary element, means between the rotary element and the said cutter frame and having adjustable connection with both, and means for adjusting the last recited means with relation to the said element and cutter frame.

204. In a machine of the class described, the combination with a main support, of a cutter support oscillatably mounted thereon, a kerf-cutter on said cutter support for making upright kerfs in an upright mine wall, means for oscillating the cutter support embodying a pitman pivotally connected therewith, a gear continuously rotatable in the same direction, a connection between said pitman and said gear embodying a crank pin adjustably connected to said gear relatively to the axis of rotation thereof, a bearing for the crank pin adjustably connected with the pitman relatively to its pivotal connection with said cutter support and to correspond with the radial adjustment of said crank pin relatively to said gear, and means for adjusting said crank pin and said bearing to vary the radius of the circle through which said crank pin moves when said gear is rotated to effect the oscillation of said cutter support.

205. In a mining machine, the combination with a main frame, of a supplemental frame pivoted thereto, cutting mechanism mounted on said supplemental frame, means for operating said cutting mechanism, means for oscillating said supplemental frame together with the cutting mechanism mounted thereon automatically and continuously, and means for regulating the extent of such oscillation while retaining one limit constant.

206. In a mining machine, the combination with a support, of a kerf-cutter mounted on said support for making an upright kerf in an upright mine wall, said kerf-cutter being oscillatably mounted on said support, automatic means for oscillating said kerf-cutter to feed the same up and down, and means for varying the extent of such oscillating movement while compelling one limit of such movement to remain constant.

207. In a mining machine, the combination with a main frame, of a supplemental frame mounted on said main frame for movement up and down relatively thereto, an upright kerf cutter mounted on said supplemental frame and movable bodily up and down therewith, automatic means for oscillating said supplemental frame to automatically feed said kerf-cutter up and down, means for varying the extent of such oscillating movement, and an abutment on the main frame for limiting the downward

movement of said supplemental frame and thereby compelling the lower limit of movement of the kerf-cutter to always remain constant.

- 5 208. In a mining machine, the combination with framework, of an under cutting kerf-cutter mounted on said framework, of a supplemental frame mounted on said framework for movement up and down relatively thereto, an upright kerf-cutter mounted on said supplemental frame for bodily movement therewith in an upright plane above said under-cutting kerf-cutter, automatic means for imparting up and down feeding movement to said upright kerf-cutter, and means for varying the extent of such up and down movement of said upright kerf-cutter while the lower limit of movement thereof remains substantially constant and 15 so as to prevent said upright kerf-cutter from coming into contact with said under-cutting kerf-cutter.

209. In a mining machine, the combination with supporting framework, of a supplemental frame mounted on said framework for movement up and down relatively thereto, an upright kerf-cutter mounted on said supplemental frame, means for moving said supplemental frame up and down to 25 secure up and down feeding movements of said upright kerf-cutter, and means for varying the extent of the upward feeding movement while the lowermost limit of said upright kerf-cutter always remains the same.

- 30 210. In a mining machine, the combination with supporting framework, of a supplemental frame mounted for up and down movement relatively to said framework, an upright kerf-cutter mounted on said supplemental frame for bodily feeding movement up and down therewith, an abutment for positively limiting the downward movement of said supplemental frame to limit the downward movement of said kerf-cutter, means for oscillating said supplemental frame to secure up and down feeding movement of said kerf-cutter, and means for varying the degree of oscillating movement while the lower limit remains constant as 35 50 determined by said abutment.

211. In a mining machine, the combination with supporting framework, of a supplemental frame mounted thereon for up and down movement relatively thereto, an upright kerf-cutter mounted on said supplemental frame and movable bodily up and down therewith, means comprising a gear wheel for positively moving said supplemental frame up and down to secure up and 45 down feeding movements of said upright kerf-cutter, said means also comprising a pitman pivotally connected to said supplemental frame and an adjustable crank pin 55 slidable radially of said gear and pivotally connected to the other end of said pitman,

and for holding said crank pin in adjusted position whereby the extent of up and down movement of said upright kerf-cutter is varied while the lower limit of such movement remains the same for various adjustments. 70

212. In a mining machine, the combination with supporting framework, of a supplemental frame mounted on said framework for up and down movement relatively thereto, a kerf-cutter mounted on said supplemental frame for bodily movement up and down with said supplemental frame, a pitman pivotally connected to said supplemental frame and extending therefrom transversely of said supplemental frame, a power transmitting wheel pivotally mounted on said framework on an axis spaced from said supplemental frame, an adjustable crank pin pivotally connected to the other end of said pitman and slidable along said pitman and radially along said wheel relatively to the axis of rotation of said wheel, and means for securing said crank pin to said pitman in adjusted position whereby the extent of up and down movement of said kerf-cutter may be varied while the lower limit of movement is maintained constant by holding such supplemental frame at its lower limit when the adjustment of said crank pin is made. 80 85 90

213. In a mining machine, the combination with a main frame, a supplemental frame, cutting mechanism mounted on said supplemental frame, means for operating said cutting mechanism, automatic mechanism for alternately and continuously raising and lowering said supplemental frame together with the cutting mechanism mounted thereon, and means for adjusting the lower limit of travel of said cutting mechanism and regulating the extent of up and down movement of said cutting mechanism, said adjusting and regulating means comprising a continuously rotating gear, a pitman pivotally connected to said gear and extending to said supplemental frame, and means for adjusting the radial position of said pivotal connection relatively to the axis of rotation of said gear. 100 105 110 115

214. In a mining machine, the combination with an elongated supporting frame, of a conveyer mounted longitudinally thereof and comprising superposed portions traveling in opposite directions to and from a forward receiving position adjacent the mine wall and to and from a rear loading position, said conveyer being mounted on said frame with a free and unobstructed space above the conveyer for the free passage of large blocks of dislodged material toward loading position, and dislodging mechanism mounted on said frame at the side of said conveyer without obstructing the passageway above said conveyer but ex- 120 125 130

tending to a position approximately above the forward receiving end of said conveyer to break down the material from an upright mine wall into a position to be received by said conveyer.

215. In a mining machine, the combination with an elongated main frame, of a conveyer extending longitudinally of said frame and comprising superposed portions traveling in opposite directions with an unobstructed space above said conveyer for the passage of large blocks of dislodged material, spaced-apart elongated frames arranged laterally of the conveyer and extending forwardly along said frame to a position near the forward receiving end of said conveyer, upright kerf cutters mounted at the forward ends of said spaced-apart frames, means for lifting and lowering said spaced-apart frames together with the cutters mounted thereon, and means mounted on said main frame for operating said cutters during the up and down bodily movements thereof.
216. In a mining machine, the combination with an elongated main frame, of a conveyer mounted thereon to extend longitudinally thereof with a free and unobstructed space above the same for the passage of large blocks of dislodged material from a forward receiving position toward loading position, an elongated supplemental frame pivotally mounted on said main frame at the rear portion thereof and to one side of said conveyer without obstructing the space above the latter, a cutter mounted on the forward end of said supplemental frame for cutting an upright kerf in a mine wall near the forward receiving end of said conveyer, means for automatically oscillat-

ing said supplemental frame together with said cutter up and down, and mechanism mounted on said main frame and connected to said cutter to operate the latter during the up and down oscillation thereof without obstructing the passageway above said conveyer.

217. In a mining machine, the combination with an elongated frame, of a conveyer extending longitudinally thereof and comprising superposed portions traveling in opposite directions to and from a forward receiving position centrally of said frame toward loading position, an undercutting kerf cutter mounted on said frame, spaced-apart side kerf cutters in upright planes extending approximately through the edges of the kerf cut by said undercutter, dislodging mechanism for breaking down material between said side cutters and above said undercutter onto the receiving end of said conveyer, said dislodging mechanism being mounted on said frame laterally of said conveyer without obstructing the space above said conveyer, said space being free and unobstructed for the passage of large blocks of dislodged material, and means for operating said undercutter, said side cutters and said dislodging mechanism without obstructing the space above said conveyer provided for the passage of material from the forward receiving end thereof to the rear end thereof.

In testimony whereof I have signed my name to this specification, in the presence of two subscribing witnesses, on this 11th day of January A. D. 1912.

EDMUND C. MORGAN.
